UNITED STATES PATENT OFFICE.

JAMES HARTNESS, OF SPRINGFIELD, VERMONT.

TURRET-LATHE.

SPECIFICATION forming part of Letters Patent No. 739,866, dated September 29, 1903.

Application filed March 20, 1901. Serial No. 52,043. (No model.)

To all whom it may concern:

Be it known that I, JAMES HARTNESS, of Springfield, in the county of Windsor and State of Vermont, have invented certain new and useful Improvements in Turret-Lathes, of which the following is a specification.

This invention has relation broadly to turret-lathes. Viewed in one aspect the object of the invention is to provide an interconvertible manually and automatically controlled turret-lathe of the type illustrated in Letters Patent No. 672,398, granted to me on the 16th day of April, 1901, with certain improvements, of which more specific mention will be made; but it may be stated that in so far as the invention relates to fluid operated or controlled machines broadly the object of the invention is to secure a more absolute control of the operative parts by eliminating the pocketing or trapping of air or gas released from the liquid in the working cylinder, to provide for greater convenience and accuracy both in manual and automatic control of the various operative parts, to provide for the more rapid turning or production of the work by a rapid dissipation of the heat which is generated by the engagement of the tools with the work, and to insure an accurate and prompt sequence of operations whereby the product of the machine will be unvarying, except as may be designed.

One of the important features of the invention is means whereby I am enabled to dissipate the heat generated by the engagement of the tools with the work. This I accomplish in some instances by the use of oil, as ordinarily, although I provide a novel mechanism for insuring the delivery of the oil with reference to the work; but in addition there-to I use a stream of air, which is delivered in proximity to the work at a relatively low temperature from a nozzle supported on the carriage, this stream of air also serving to free the back-rest of chips. The temperature of the air may be reduced in any suitable way; but for this purpose I utilize the air-motor, by means of which I drive the lathe-spindle. After refrigerating the air and delivering a stream thereof against the work I am not only enabled to rapidly dissipate the heat and keep the temperature of the tool and work at a minimum, but am also able to free the

back-rest from chips, as stated, making it possible to employ a form of roller back-rest such as shown in my Patent No. 543,551, 55 dated July 30, 1895. It is desirable to employ a roller back-rest, since the friction of the ordinary back-rest at times generates as much heat as the cutting-tool; but owing to the liability of a chip being rolled or carried between the back-rest and the work and forcing the work to spring against the tool, and thereby cause a depression in the work, such roller back-rests have not come into wide and general use. It will be seen, therefore, that 60 by always keeping the back-rest free of chips by the employment of a stream of air it is possible to secure the advantages incident to such back-rest without its disadvantages. In addition to the air stream freeing the work 70 from small particles or chips it permits the employment of a templet for shaping the work. Consequently a sample of the work to be produced may be itself used as a templet. The oil and the air are fed to the work by a 75 double pipe, one leading from the motor-exhaust and the other from a convenient source of oil-supply.

Another feature of the machine which I regard as of importance is the provision of 80 mechanism for controlling all of the operative parts of the lathe, said mechanism including a plurality of stops, the location of which may be recorded in any convenient way to guide the operative in adjusting the machine 85 in case it be desired to reproduce in the future the work manufactured by the machine at any particular time. There are many ways by which this may be accomplished; but in its simplest form this mechanism consists of a controller having a plurality of 90 stops adapted to be located thereon in predetermined positions. Each stop may be placed in any one of a number of positions upon the controller, each position being designated by 95 a symbol or otherwise, so that it may be indicated upon a record-sheet. The various parts of the lathe must in order to permit of the production of a piece of work of a certain shape operate in a predetermined sequence. 100 Consequently after the stops on the controller have been once located to cause the parts to operate in said sequence their relative positions may be made a permanent rec-

ord for future use. So far as I am aware this has never been possible upon a turret-lathe or other equivalent machine, it having been previously necessary for the operator to 5 spend a great deal of time in adjusting the machine for each particular piece of work to be produced. In this particular embodiment of the invention the controller includes a yieldingly-driven shaft, upon which is placed 10 one or more drums or cylindrical supports each having one or more series of apertures for the reception of one or more stop-pins. Each series of apertures may be designated by a suitable symbol, such as a letter, and 15 each aperture which determines the position of one of the stop-pins may be numbered, said apertures being numbered in sequence. Thus the locations for the stops may be recorded as A' B' C', &c. The first apertures 20 of the series are substantially in alinement; but this is not essential.

Inasmuch as I employ, as stated, a yieldingly-driven controller, I make use of an escapement mechanism to coöperate with certain of the stops thereon. The said escapement mechanism presents certain features of improvement over the mechanism illustrated in my application hereinbefore referred to and includes two movable abutments, which 25 30 I have termed "latches," one being an oscillatory or rotative latch and the other a swinging latch. The swinging latch is operated solely by the turret and only when the latter has reached the extreme of its travel away 35 from the chuck, whereas the rotative or oscillatory latch may be controlled by other parts, such as the turret-slide, the stop which determines the length of the work fed through the chuck, and the cutting-off tool, &c. Inasmuch as the operation of the swinging latch 40 permits the forward feeding of the turret in this embodiment of the invention, I provide a knock-off or trip for the swinging latch by which its operation is made impossible except at the proper time, and consequently I 45 prevent the turret from being fed forward toward the work, except in proper sequence. Broadly speaking, the trip or knock-off mechanism is controlled by the position of the turret and is actuated by the index-pin, which 50 holds the turret against rotation. Coöperating with the swinging latch is a series of stops placed in predetermined positions upon the controller, and each one of the stops is at 55 the proper time struck by a "hammer," as I term it, to cause it to disengage the latch and permit the rotation of the controller-shaft. The turret is usually provided for the reception of six tools, and I therefore provide the 60 controller with a series of apertures for the reception of a similar number of stops. The swinging hammer is swung across the path of the stops, its lateral location being controlled by a cam-shaped surface of the turret, and it is so arranged with reference to 65 the index or locking pin that when the latter moves to operative position after the rotation

of the turret the hammer receives an impulse which causes it to strike against one of the stops to free the latch and permit a partial 70 rotation of the controller. By the employment of this mechanism it is impossible for the turret to be started forward toward the chuck if the turret is not in its proper position or if the order of operations has been disturbed. 75

In order to prevent the passage of more than one stop on the controller at a time, there being a stop for each operation of the parts of the machine, I employ the "oscillatory" or "rotating" latch, so called. This latch is so arranged that the engagement of one stop therewith moves the latch in position to prevent the passage or movement of another stop in the same row or series. By 85 means which I shall describe the rotary latch is given a partial rotation after it has been disengaged by the stop to bring it into operation for the passage of the next succeeding stop. 90

The illustrated embodiment of my invention is provided with improved fluid-operated mechanism for the turret-carriage, and it differs from the mechanism illustrated in my various patents and in my said application 95 in the employment of liquid on both sides of the piston in the cylinder, by the location of liquid tanks above the plane of the carriage-cylinder to prevent the trapping of air, and by the combining of the fluid regulator or 100 meter and the controlling-valve in one casting, which may be bolted directly to the tank to dispense with the employment of many pipe connections. By locating the tanks above the plane of the cylinder and by having a continuous rise in the pipes leading 105 from the tops of the cylinders to the tanks I prevent the accumulation of air or other gases that may be freed from the liquid in the cylinder and pipes. 110

The fluid-regulator is controlled by stop mechanism on the controller-shaft somewhat similar to that described in my Letters Patent No. 672,398, the details of the mechanism being altered to suit the particular requirements which I have had in mind. In some fluid-operated machines there is a jerky motion of the carriage caused by the metering or regulation of the fluid, and consequently one of the features of my present invention 115 is means for insuring an even pressure on the operating-piston. This mechanism includes a cushioning device connected with each of the pipes leading from the valve to the turret-feeding cylinder, consisting of a 120 casing provided with a spring-pressed diaphragm and also with means for adjusting the tension of the spring, whereby the spring-tension can be so adjusted during the operation of the machine that it is just sufficient 125 to cause the continued flow of liquid in the interim between the reciprocations of the operating member or piston of the meter and 130 is at the same time weak enough to yield un-

der the hammer effect of the charge of liquid. The extent of vibration of the diaphragm is controlled by adjusting devices by which the extent of the cushioning of the charge from the meter is directly regulated. The advantage of this cushion over the old air-chamber in common use on pumps or accumulators is that the extent or degree to which it is adapted to yield is easily controlled. The employment of an air-pump would by compression of the air permit the turret to stop temporarily under a great resistance and then cause it to jump as soon as the resistance was decreased, whereas this device limits the extent of the rapid movement to the amount of a single charge from the meter. In addition to these various features I provide an improved back-gear by means of which I am enabled to secure the transmission of greater driving power without unduly increasing the strain on the driving-gears or the spindle, both of which are injurious to the lathe. According to the present invention I have provided a balanced drive by which the strain on the gear-teeth is greatly reduced and that on the bearing is rendered *nil*. This mechanism includes two sets of gears arranged on both sides of the spindle and mounted in a holder which has a free movement to divide the working strain equally on both gears. The holder for the gear-arbors is constructed in the form of a hood to protect the gears from chips.

The work-receiving mechanism is somewhat similar to that described in my said Letters Patent, differing therefrom, however, in the fact that I do not depend upon a spring for withdrawing the receiver from its operative position. I found that it was necessary to employ a very strong spring and that the action thereof was at times relatively slow. Consequently in the present invention I provide for the receiver being positively moved to inoperative position by the action of the turret-carriage, thus reducing the number of parts and greatly simplifying the mechanism.

I further provide in this present invention a cutting-off tool, which is located below the work and rises from the bed to present the tool to the under side of the work. The tool is moved rapidly to operative position by fluid-operated mechanism, a regulator being employed to control the flow of the liquid during the feeding of the tool when acting upon the work. I have provided certain improvements in the regulating mechanism, for I have found that a slight difference in the resistance of the cutting-off tool greatly affects the flow of liquid through the regulator, so that the operating-pressure varies inversely with the resistance to the action of the tool. Consequently the regulator in the present invention is so constructed as to provide for the pressure on the tool increasing in direct accordance with the increase in resistance. This mechanism for securing a differential pressure is automatic in its opera-

tion and provides for decreasing the length of time hitherto necessary for cutting off the finished work. The fluid-operated mechanism for actuating the cutting-off tool may be controlled both manually and automatically, the automatic mechanism including a plurality of stops on the controller by which a rapid movement of the tool toward operative position is arrested when it is about to engage the work. The manually-operated mechanism is arranged to be operated by the workman and includes certain novel features, which I shall hereinafter describe in detail.

Still another important feature of the invention is the mechanism by which communication is effected between the escapement before referred to and the various parts of the machine with which it should be connected or by which it is controlled. This means of communication consists of a conduit having at each end a movable member, such as a diaphragm or piston, whereby the vibration of one of them will, through the medium of a column of fluid contained in the conduit, cause a similar vibration of the other. So far as I am aware I am the first to have provided a machine having this means of communication or connection between two operative parts, and inasmuch as it is susceptible of many modifications I intend in no wise to limit myself to any particular form thereof, for it is obvious that the effect may be gained not only by increasing the pressure on the contained fluid, but likewise in decreasing the same, and consequently my invention may be said to comprehend, broadly, means of communication consisting of a conduit with a movable member at each end the pressure on the fluid in which may be varied to impart an impulse from one of the members to the other. I employ this means of communication in the present instance for causing the rotation of the rotary latch member, it being controlled by the carriage, the work-feed, and the cutting-off tool.

In order to protect the turret stop-bars, which are similar to those described in my said Letters Patent, and to render it possible for the oil and fine particles that would otherwise accumulate on the stops to flow therefrom, I employ a sliding shield, which loosely covers the stop-bars, the latter being arranged in a shallow tray supported on the bed. The shield or cover is adapted to be moved back and forth with the turret during a portion of the turret travel.

I have also provided improved devices for reducing the shock caused by the constant stopping and starting of the turret by modifying the form of the rack and of the pinion employed to impart the rotary movement to the turret. By this mechanism I am enabled to start the turret slowly, give it a quick movement during the middle of its stroke, and gradually reduce its speed until it is relatively slow at the time it is arrested in its rotary travel by the locking or index pin. The

employment of this mechanism enables me to cause a double movement of the turret and provide for the skipping of one of the tools in case it is desired.

5 In addition to the foregoing I have provided numerous other improvements, which are hereinafter described in detail; but it will be understood that many of them may be used separately or on various other types of 10 turret-lathes without departing from my invention and that I intend in no wise to limit myself to the combinations shown in the following specification or to the particular details of construction.

15 The phraseology which I have seen fit to employ in the specification and the appended claims is for the purpose of description and not of limitation, and I reserve the right to apply all known mechanical equivalents 20 which may be used for the parts illustrated and described as comprehended by my invention. To secure a better understanding of the machine as a whole and its relation to previous machines, reference may be had to 25 my prior patents, No. 635,887, dated October 31, 1899; No. 635,888, dated October 31, 1899, and No. 637,401, dated November 21, 1899, in addition to my said Patent No. 672,398, hereinbefore referred to.

30 Referring to the drawings, Figure 1 represents a side elevation of a turret-lathe constructed in accordance with my invention and equipped with my improvements. Fig. 2 represents an elevation of the right end.

35 Fig. 3 represents an elevation of the left end. Fig. 4 represents a plan view of the machine. Fig. 5 represents a rear elevation of the head end of the machine. Fig. 6 represents a plan view of the same. Fig. 7 represents a vertical 40 section through the spindle and the mechanism for imparting motion thereto. Fig. 8 represents a horizontal section through the same. Fig. 9 represents in detail part of the back-gear. Fig. 10 represents a collar on the spindle. Fig. 11 represents a transverse section 45 through the machine and shows the holder for the back-gearing. Figs. 12 and 13 represent a section of the holder and show the back-gearing. Fig. 14 represents the back-gearing 50 in inverted plan view with the lower casing removed. Fig. 15 represents a section on the line 15 15 of Fig. 11. Fig. 16 represents a holder with parts removed. Figs. 17 and 18 represent improved gearing for imparting a 55 yielding rotation to the controller-shaft. Fig. 19 represents a portion of the bed, the carriage, and the escapements for the controller-shaft. Fig. 20 represents a plan view of the carriage with a portion of the turret in section to illustrate 60 the cam-surface which governs the action of the swinging latch. Fig. 20^a illustrates the pawl and ratchet for rotating the turret. Figs. 21 and 22 illustrate the mechanism for setting the rotative latch to operative 65 position. Fig. 23 is another view of the rotary or oscillatory latch and the device for operating the same. Figs. 24 and 25 illus-

trate the operations of the swinging latch. Fig. 26 represents a transverse section of a portion of the lathe, illustrating the swinging latch, the hammer, and the means for operating and controlling it. Fig. 27 represents a similar section on a different plane. Fig. 28 is a section on line 28 28, Fig. 26, looking downwardly. Fig. 29 represents the same 75 parts in side elevation. Fig. 30 illustrates the stop-bars in the swinging tray. Fig. 31 illustrates the pin which coöperates with one of the stop-bars on the swinging tray for cutting off the supply of accelerating-fluid. Figs. 80 32 and 33 illustrate the mechanism for actuating the index-pin and also the connection between the index-pin and the swinging trip-hammer. Fig. 34 illustrates the rack and pinion for imparting a differential rotating 85 movement to the turret. Fig. 35 is a detail view of the index-pin mechanism. Fig. 36 is a section taken longitudinally of the machine and illustrates the cutting-off tool, the work-receiver, the chuck opening and closing device, and the stop mechanism for limiting the work-feed. Fig. 37 is a section taken transversely of the machine and illustrates the same parts. Fig. 38 represents a transverse section of the machine and illustrates 90 the cutting-off tool in detail. Fig. 39 represents the cutting-off tool and fluid-operated mechanism by which it is actuated. Fig. 40 represents a section on the line 40 40, Fig. 38, looking toward the right. Fig. 41 represents the stops on the vertical bar for 100 controlling the controller-escapement. Figs. 42 and 43 show the piston for the cutting-off tool by which the flow of fluid to the cylinder for said tool is regulated. Fig. 44 represents the piston in section and illustrates the projection engaging with the pin connected to the valve. Fig. 45 represents a partial horizontal section through the lathe and represents the cutting-off tool and the 105 parts for controlling its operation and also the operation of the controller. Fig. 46 is a section through the same on a lower plane. Fig. 47 represents a horizontal section through the piston for the cutting-off tool and represents the top plan view of the cylinder thereof, the liquid-tank being also represented. Fig. 48 represents a section through the valve 110 by which the supply of liquid to the cutting-off tool is regulated. Figs. 49 and 50 represent, respectively, sections on the lines 49 49 and 50 50 of Fig. 48. Figs. 51 to 56 illustrate different positions of the valve. Fig. 57 illustrates the mechanism operated by the controller for controlling the supply of liquid 115 to the cutting-off tool. Fig. 58 represents the same in a different position. Figs. 59 and 60 illustrate the different positions of the valve-stem. Fig. 61 represents the projection on the piston for the cutting-off tool, said projection being adapted to engage the connecting-rod shown in Fig. 70. Fig. 62 represents the rear elevation of a portion of 120 the lathe and illustrates the receiver for the

work and the mechanism by which it is actuated. Fig. 63 represents the same with the turret in its extreme of movement away from the chuck. Figs. 64 and 65 illustrate the positions of the longitudinally-movable rock-shaft, which, as will be explained, is adapted to rock to permit its engagement by the carriage to effect the operation of the work-receiver. Fig. 66 represents the stop-bars on the bed and the dogs on the carriage which are engaged therewith to limit the forward movement of the carriage. Figs. 67 to 71 illustrate in detail the parts shown in Fig. 66. Fig. 72 illustrates the diaphragm at the end of the conduit between the dogs and the escapement for the controller-shaft. Fig. 73 represents the front elevation of the left end of the lathe and shows the automatic belt-shipper. Fig. 74 represents a transverse section through the lathe and illustrates the same parts. Fig. 75 represents a plan view of the belt-shipper mechanism. Fig. 76 illustrates the pipe connection for the fluid from the valve to the belt-shipping cylinder. Fig. 77 represents a plan view of the belt-shipping cylinder and piston. Fig. 77^a represents a longitudinal section through the parts shown in Fig. 77. Fig. 78 represents in plan view the controller and the valves operated thereby, said valves controlling the mechanism for shipping the belt, for opening and closing the chuck, for operating the tool-closer, for controlling the cutting-off tool, and for controlling the movement of the turret-carriage. Fig. 79 represents a longitudinal section through the same. Fig. 80 represents a section on the line 80 80 of Fig. 78. Fig. 81 represents the valves for the belt-shipping and the chuck opening and closing mechanism. Fig. 82 illustrates a section through the belt-shipping valve. Figs. 83 and 84 illustrate the cam-pins on the detachable valve-collar. Fig. 85 illustrates in section the valve mechanism for the tool-closing mechanism. Figs. 86 and 87 illustrate the mechanism operated by the controller for shifting said valve. Figs. 88 and 89 illustrate different positions of the valve. Figs. 90 and 91 illustrate the said valve mechanism in detail. Figs. 92 and 93 illustrate the controller for the cutting-tool valve. Fig. 94 is a diagrammatic plan view of the pipe connections on the lathe. Fig. 95 represents a front elevation of the same. Fig. 96 represents the valve for the rotary latch, which is controlled by a diaphragm. Fig. 97 represents the same in section. Fig. 98 represents an end elevation of a front portion of the lathe with the mechanism for controlling the meter by which the supply of fluid to the carriage-feeding cylinder is regulated. Fig. 99 represents a front elevation of the same. Figs. 100, 101, and 102 illustrate the mechanism for regulating the speed of the motor in case one be employed for initially driving the lathe. Fig. 103 illustrates the fluid-tank for the carriage-feeding cylinder and also the valve mechanism for the

fluid regulator or meter and for the cylinder. Fig. 104 illustrates the valve for controlling the fluid in position to permit free flow of the liquid to the cylinder from the tank, and vice versa. Fig. 105 represents the same valve in position to deflect the liquid through the meter. Fig. 106 illustrates the valve in neutral or closed position. Fig. 107 illustrates the valve-casing in longitudinal section with the valve-plug in side elevation. Fig. 108 illustrates another longitudinal section through the tank and illustrates a portion of the valve-plug which controls the supply of air to the tanks. Fig. 109 shows the same with the valve-plug in different position when the turret-carriage is stationary. Fig. 110 represents a section of the valve-casing on the line 110 110 of Fig. 107. Fig. 111 represents that portion of the valve-plug which controls the passage of the liquid through the meter to the cylinder, being a section on line 111 111, Fig. 110. Fig. 112 represents a vertical section through the valve-casing and illustrates the ports or conduits for the liquid from the tank to the valve. Fig. 113 represents the valve-casing and the meter in side elevation looking from the left end of the machine. Fig. 114 represents the stops for regulating the movement of the proper pistons in the meter or regulator, a portion of the valve-casing being in section. Fig. 115 represents a horizontal section through the liquid-tanks. Fig. 116 represents a meter or liquid-regulator in vertical section on line 116 116 of Fig. 115. Fig. 117 represents a section on the line 117 117 of Fig. 116. Fig. 118 represents a plan view of the valve with tank removed. Fig. 119 illustrates the seat for the regulator or meter valve. Fig. 120 represents the automatic device for cushioning the charges of liquid admitted to the carriage-feeding cylinder through the meter, and thereby effecting an even movement of the carriage. Figs. 121 to 128 illustrate the sliding shield for covering the stop-bars on the bed by which the forward travel of the turret is checked. Figs. 129 to 138 represent the templet-controlled turner and the roller back-rest for the work. Fig. 139 illustrates the air and oil conduits by which air or oil is supplied to the work and showing in dotted lines a position which will be hereinafter explained. Fig. 139^a represents an enlarged sectional elevation of a portion of the same.

Referring to the accompanying drawings, which, as stated, illustrate one embodiment of the invention, so far as many features of the invention are concerned they do not broadly differ from the turret-lathe illustrated in my said Letters Patent No. 672,398—that is to say, the lathe has the essential elements of a bed, a spindle carrying a chuck, a roller-feed, a carriage on the bed adapted to be moved on ways toward and from the chuck, a turret rotatively mounted on the carriage and having provisions on its flat upper face

for the reception of a plurality of operating tools, fluid-operated mechanism for moving the turret-carriage on the bed, a cutting-off tool actuated by fluid-operated mechanism, 5 an automatic work-receiver, and devices for controlling the operative parts either manually or automatically.

General construction.—Referring now to the drawings, the hollow bed is indicated as 10 a whole at 200, it being provided with the usual ways or shears upon which slides the carriage 201, the latter being equipped with a flat-top turret 202. The shears for the carriage are indicated at 203, and the carriage 15 is fed first in one direction and then in the other by fluid-operated mechanism, including a cylinder and piston located under the bed. The hollow spindle, through which the work in the form of a bar passes, is best shown in 20 Fig. 7, being indicated at 204. It is journaled in boxes 205, supported on standards at the left or head end of the lathe.

Spindle-driving mechanism.—The driving mechanism includes a counter-shaft 206, journaled in the bed and equipped with a wide belt-pulley 207, from which power is transmitted to either of two pulleys 208 and 209, connected to the spindle by mechanism which I shall describe. Between the pulleys there 25 is a loose pulley 210, with which the belt 211 is shown as engaged in the last-mentioned figure. I may provide means for driving the counter-shaft in any of several different ways. For instance, in Figs. 3, 5, and 11 I have 30 shown a shaft as being rotated by a compressed-air engine located at 212. The crank-shaft 213 is provided with a sprocket-wheel 214. The sprocket-chain 215 connects the sprocket 214 with the sprocket 216 on counter-shaft 206, Figs. 3 and 7. This air-engine 35 may be of any convenient or suitable type, by which sufficient power is transmitted to insure the proper rotation of the spindle. I prefer to use an air-motor, for the reason that I 40 employ the exhaust to reduce the temperature of the tool and work; but if it be desired to employ only oil as a cooling agent I may use a gasoline, explosive, or electric motor in lieu of that shown. Another means for driving 45 the counter-shaft consists of a shaft 217, which may be rotated by any suitable means, from which power is transmitted to shaft 206 through the medium of gears 218 and 219. In addition to these the shaft 206 has provisions 50 220 at its end whereby it may be coupled to a suitable driving-shaft.

Back-gear mechanism.—The pulley 208 is keyed directly to the spindle, whereas that at 55 209 is loose upon the spindle, but is provided with a hub by which it is keyed to the gear 221. Located opposite to each other are two arbors 222 222, which are journaled in the holder 224. On these arbors are secured two spur-gears 223 and 223^a, both intermeshing 60 with the gear 221, and two gears 225 and 226, intermeshing with the gear 227, keyed to the spindle 204. The holder is loosely mount-

ed, so that the gears have a limited movement relatively to the spindle, being secured to a support 228, having a downwardly-projecting bar 229, whose lower end fits loosely in a socket 230. The holder is held from dropping by the engagement of the gears, but is capable of a certain amount of loose movement. Owing to this loose movement 75 of the holder, the gears may be all caused to simultaneously engage the teeth of their intermeshing gears, so that the work will be equally performed by those on both sides of the spindle. From this description it will be 80 observed that I have provided transmitting-gearing by which greater driving power may be transmitted to the spindle without unduly increasing the strain on the driving-gears or the spindle-bearings. Hitherto it has been customary to employ a large driving or "bull" gear on the spindle, whereby the tooth speed of the gear was relatively great. By employing, however, the small gears the tooth speed of the gear 227 is greatly reduced, 90 while at the same time I provide a balanced drive, which eliminates the strain on the bearings and reduces the strain on the gear-teeth. It is obvious that the exact location of the transmitting-gears of the back gearing 95 is immaterial and that they may be above or below the spindle with equal facility. The holder itself is in the form of a shield or hood, which protects the gears from chips. It is held against lateral movement by collars 232, 100 placed loosely on the spindle and having guides 233, in which it is adapted to slide. The support 228 is connected to the holder by screws 234, as shown in Figs. 15 and 16.

I do not herein claim the "balanced-drive" 105 mechanism or back-gear mechanism.

Chuck opening and closing mechanism.—The chuck is indicated as a whole at 235, (see Figs. 7 and 74,) it being of any preferred construction. The movable member of the 110 chuck is adapted to be moved longitudinally of the spindle by levers 236, fulcrumed at 237 and having pins engaging the groove 238 in said movable member. To the cross-bar 239, which connects said levers, is loosely 115 secured the end of the piston-rod 240, passing through a stuffing-box into the cylinder 241, the piston of which is indicated at 242. By suitable mechanism, which I shall herein-after describe, fluid is admitted first to one 120 side of the piston through pipe 611 to open the chuck and permit the feeding of the work and then to the other side of the piston through pipe 612 to close the chuck.

Work-feed.—The roller-feed for the work, 125 which may be also of any desired construction, is indicated at 243 and includes a rotatable member 244 on the spindle, having a plurality of cavities or engaging members to be engaged by a vertically-arranged pin 245, by which 130 the said member may be held against rotation while the spindle continues to rotate, and thereby effect a feed of the work. This pin enters a tubular rod 246, which is held down-

wardly against a longitudinally-movable bar 247 by the spring 248. Said bar is passed loosely through an aperture in the bar 229, being connected at one end to a cross-bar 249 between the levers 236, and it is provided with a cavity 250, in which the lower end of the rod normally rests. The spring indicated at 251 is shown in dotted lines in Fig. 7 as interposed between the end of the pin 245 and the bottom of the socket in the rod 246. When the levers 236 are forced to the right in Fig. 7 to open the chuck, the lower end of rod 246 rides up on the cam-surface 252, and the pin 245 is forced into one of the notches in the member 244 to hold said member against rotation.

Belt-shipping mechanism.—I shall now proceed to describe the mechanism by which the belt 211 is automatically shifted from pulley 208 to pulley 209, and vice versa, reference being had to Figs. 73 to 77^a, inclusive. The shipper consists of a piston which at its ends is passed into cylinders 261 and 262, formed on or bolted to the front of the bed 200. This shipper is provided with two lugs 263 263, between which the belt travels, as best shown in Fig. 75, so that by moving the piston in one direction or the other the belt may be moved laterally from one pulley to the other. The opposite ends of the two cylinders are connected to a suitable valve mechanism by pipes 264 and 265, so that fluid may be introduced into one cylinder and exhausted from the other to permit the operation of the shipper. The valve mechanism may be operated manually or automatically, the machine in this respect being interconvertible, as will be explained. I shall reserve the description of this and other valve mechanisms until I have described the various operative parts of the lathe, since some of the said valve mechanisms are similar to each other, and one description will therefore suffice for several. It is desirable to here state, however, that the valve mechanism for the shipper is moved to position to shut off the supply of fluid from the operating side of the piston when the shipper has traveled a proper distance, and to this end said shipper is provided with a lug 266, adapted to travel between two stops 267 and 268 on the rod 269, mounted in a guide 270 and connected to the bell-crank 271, which is in turn connected by a rod 272 to an arm 273 on the valve. (See Figs. 78 and 79.)

Turret-carriage-operating mechanism.—The piston and cylinder into which liquid is introduced for feeding the turret-carriage are shown in Figs. 38, 74, 121, and 122. The cylinder 253 is formed in the casting 254 and bolted to the inside of the bed 200, as shown in Fig. 38. The piston is indicated at 255. The piston-rod 256 passes through a stuffing-box, being connected through the medium of the lug 257 with the carriage 201, as shown in Figs. 121 and 122. The pipes through which liquid is introduced to the cylinder are connected to the opposite ends thereof and

are indicated at 258 and 259, respectively. The pipe 259 is laid in a groove formed in the side of the casting, as shown in Fig. 38. 70 The valve mechanism by which the passage of fluid to the cylinder is controlled will be hereinafter fully described in detail, it being arranged to be operated either manually or automatically. 75

The fluid-operated mechanism is so regulated or controlled that the carriage is moved rapidly away from the chuck and then toward the chuck until it is in position for the tool to begin operating upon the work, whereupon the supply of fluid to the cylinder is reduced, and the carriage is caused to feed slowly during the time that the tool is at work. When the limit of feed toward the chuck is reached, the carriage is automatically stopped, the valve mechanism being shifted to cause the carriage to be then moved away from the chuck. To accomplish this, I provide a plurality of stop-bars adjustably secured in a shallow trough in the bed beneath the carriage, the said stop-bars being similar to those illustrated in my said Letters Patent No. 672,398. The said stop-bars are indicated at 297 and are illustrated at Figs. 4, 20, 66 to 69, 121, and 122. Each bar is 95 notched at its inner end to receive a dog 298, there being for each tool one stop-bar and one dog. Said dogs are all loosely mounted upon a stud 299 in a frame 300, secured to the carriage below the turret, as shown in Fig. 66. Normally the dogs move above the tops of the outer edges of the stop-bars until one of them drops into a notch thereon, and as the turret continues its movement the dog is held stationary and is caused to actuate a 100 device by which the supply of fluid to the feeding-cylinder is controlled. Only one dog at a time is permitted to ride upon a stop-bar, the others being held out of engagement by a series of pins 301, arranged horizontally 110 in the gib, as shown in Fig. 66. These pins are arranged in different vertical planes, and each one is controlled by a cam-surface on the periphery of the turret. As the turret rotates the pins enter the cavities formed by 115 the cam-surfaces one at a time and permit their corresponding dogs 298 to drop into operative position, as subsequently explained. The pins bear against fingers 302, projecting upwardly from said dogs, as shown. The 120 rear ends of the dogs bear against the lever 303, fulcrumed in the frame 300, and when the movement of one of the dogs is arrested by its engagement with the notch in one of the stop-bars its rear end forces the lever 125 303 rearwardly, whereupon a finger 304 on said lever engages a rod 1305 and by releasing the controller-shaft permits the operation of the controller-valve and stops the advance of the turret. I shall reserve the description of the action between the pin 1305 and the controller-shaft until hereinafter. 130

In order to protect the stop-bars from chips, I employ a shield or cover therefor which

has a limited movement relative thereto. The said shield or cover comprises two parallel side bars 305, connected by a flat plate 306. These side bars slide in guides 307 in the trough which holds the stop-bars, as best shown in Figs. 126 and 127. The plate 306 is shorter in length than the stop-bars and is adapted to cover the forward ends of the latter, being carried toward the chuck by the turret to prevent the dropping of chips thereon, as stated. The ends of the side bars 305 are secured by bolts to a cross-bar 308, (see Fig. 125,) which slides in guides formed on the shears 203. The carriage is provided with a downwardly-projecting pin 309, which during the forward movement of the carriage is adapted to engage the end of the plate 306 and move it forward, as shown in Fig. 124. In order to carry the plate rearwardly, there is attached to the under side of the plate a flat spring 310, which projects beyond the plate and is provided with a lug 311. (See Figs. 124 and 125.) When the turret slide or carriage is moved away from the chuck, the shield or guard moves with the turret, and in order to arrest the movement of the shield to prevent the front ends of the stop-bars from being uncovered the trough for the stop-bars is provided with a socket 312, into which the lug 311 is forced by the spring 310 when the shield reaches proper position, whereupon the pin 309 is permitted to slide over the top of the lug without carrying the shield with it. Such oil and particles of chips which fall upon the shield may flow therefrom without being deposited upon the stop-bars, the side walls of the trough being beveled for this purpose. The movement of the carriage away from the chuck is arrested through the medium of the rack-bar 282 engaging the stop-bar 283, as subsequently explained.

Turret rotating and locking mechanism.—

The mechanism by which the turret is rotated and then locked in position is illustrated in Figs. 1, 4, 20, 20^a, 32, 33, 34, and 35. The turret itself, as has been stated, is of the flat type, and it is provided with a central stud or bearing 275, projecting downward into the carriage. The periphery of the turret is secured against vertical movement by a gib 276 in the manner common to my machines. On the journal-bearing 275 (see Fig. 20) is journaled a ratchet 277, with which a pawl 55 or pawls 2771 (see Fig. 20^a) on the turret are adapted to engage. This ratchet is formed with a series of cam-teeth 278, 279, 280, and 281, which may be engaged in succession by the teeth of a rack-bar 282, mounted to slide 60 in the carriage. This rack-bar projects from the end of the carriage and is adapted to engage a stationary bar 283, secured adjustably to a cross-bar 284 at the end of the bed. When the carriage is moving away 65 from the chuck, the end of the bar 282 engages the stop-bar 283 and is held against further movement, and as the carriage con-

tinues to move the index-pin, to be described, is disengaged from its bushing, and the cam-teeth of the rack-bar engaging the teeth of the ratchet cause the latter to rotate sixty degrees (in case six turret-tools are employed) to bring another tool into operative position in relation to the work. It will be observed that the teeth on the ratchet are relatively distant from each other and are peculiarly shaped, the purpose of this being to cause a gradual movement of the ratchet, which increases in rapidity during the first part of the partial rotation and which then decreases in rapidity during the latter part of its partial rotation, so that it is moving very slowly by the time its extreme of movement is reached, the purpose of this being to lessen the jar in starting and stopping the rotation of the turret. Referring to Fig. 34, it will be seen that the tooth 278 when the parts are in normal position has but a small portion projecting into the path of the end of the rack-bar and that the side of the tooth is at an acute angle to the path of movement of said bar. Consequently the movement caused by the engagement of the bar with the tooth is relatively slow. When the next tooth 286 on the bar engages tooth 279 on the ratchet, the movement is more rapid, said movement decreasing, however, in rapidity as the ratchet swings through its arc of movement and as the tooth 279 reaches an angle more and more acute to the path of travel of said bar 282. The other teeth on the ratchet and on the bar are provided in order that I may swing the ratchet and the turret to an angle of one hundred and twenty degrees, so as to skip a tool in case a number of tools is employed less than the whole number. The co-action of the rack and ratchet is in the nature of that of a cam and lever or cam and slide and, as stated, prevents the constant shock to the machine. The index-pin is indicated at 287. It is mounted in a bushing 288 in the carriage, and its upper beveled or tapered end is adapted to enter into a bushing 289 in the turret, it being held upward by a strong helical spring 290. The mechanism for depressing said pin includes an arm 291 and a rock-shaft 292, journaled in the carriage, as shown in Fig. 32. A lever 293 is fulcrumed on a stud 294, projecting downward from the carriage, and its free end rests upon arm 291. This lever has a roll 295 in the path of the swinging pawl 296 on the end of the rack-bar. When the rack-bar is held stationary and the carriage continues its retrograde movement, the pawl 296 engages the roll 295, depresses the lever 293, and forces downward the arm 291, with the result that the index-pin is depressed and disengaged from the bushing 289. The pawl is hung on a pivot, so that when the rack-bar moves back to proper position during the forward movement of the carriage it rides over the roll, as described in my Letters Patent No. 672,398. To return the ratchet to the posi-

tion shown in Fig. 34 after it has rotated the turret through an arc of sixty degrees, the rack-bar is temporarily held during its forward movement by spring-latches 1296 on the bar 283, said latches engaging the end of the rack-bar, as ordinarily.

The controller-shaft and its driving mechanism.—The controller includes a shaft 313, which is journaled in bearings in the front 10 of the lathe, said bearings being indicated at 314 and 315, respectively, Fig. 1. The said shaft is yieldingly driven from the shaft 206. To this end said controller-shaft is equipped 15 with a worm-wheel 316, intermeshing with a worm 317 on a transverse shaft 318, as best shown in Figs. 3, 17, and 18. Said shaft 318 is journaled in suitable bearings 319 and 320, the former being supported upon shaft 206 and the latter by the controller-shaft and 20 held from movement by a bracket 321, projecting forward from the bed 200. On the shaft 318 is a worm-wheel 322, intermeshing with and driven by a worm 323 on the shaft 206. The worm 317 is loose upon the shaft 25 318 and is formed with clutch-teeth 324 to engage the clutch member 325, pinned to the said shaft 318. A spring 326 is adapted to normally hold the clutch-teeth 324 on the worm in engagement with the teeth 325 upon 30 the clutch member. The worm-shaft 318 normally rotates in the direction of the arrow *a* to effect a movement of the controller-shaft in the direction of the arrow *b*, said worm-shaft being driven continuously. If 35 the controller-shaft 313 be permitted to rotate continuously, the spring 326 will seat the worm 317 against the clutch 325, and said worm will continue to drive the worm-wheel 316. When the shaft 313 is held against rotation, however, the continuous rotation of 40 the shaft 318 will cause the worm 317 to be fed or screwed against the pressure of the spring 326 rearwardly from the clutch 325 until it is entirely free from engagement, 45 whereupon it will cease rotating, and the motion of the worm-wheel 316 will at once cease. The action of the worm and worm-wheel at this time is similar to the action of a worm-and-rack gear. As soon as the escapement 50 releases the controller-shaft the spring 326 will force the worm against the clutch 325, imparting a slight yielding initial jog or movement to the controller-shaft. The spring 326 is therefore strong enough to overcome all resistance to the rotation of the controller-shaft 55 except when it is held positively by a stop. The controller-shaft is provided with two drums, cylindrical supports, or stop-carriers, indicated at 328 and 329, (see Fig. 1,) and also 60 with another stop-carrier 330, with which cooperate the escapements. The stop-carrier 328 controls the amount of the charges delivered by the fluid regulator or meter. That at 329 controls the operation of the valve 65 mechanisms for the turret-feeding cylinder, the chuck opening and closing cylinder, the belt-shipping cylinder, the cylinder for the

cutting-off tool, and the cylinder for the tool closer. The controller-shaft 313 is permitted to rotate step by step, the escapements being actuated at the completion of each operation, and as the controller-shaft rotates it operates one or another of the valve mechanisms to permit the next operation to follow in proper sequence.

The escapement for the controller-shaft.—There are two escapements, one controlled and operated by the turret and the index-pin and one controlled and operated by various other parts of the machine. That escapement 70 which is controlled by the turret I term a "swinging latch" to distinguish it from the other, which I denominate a "rotary" latch.

The swinging latch.—The swinging latch and the parts by which it is operated are 75 shown in Figs. 19 to 29. The stop-carrier 330 is provided with nine series of apertures, there being one series of apertures for the trip pins or members for the swinging latch to engage, six series of apertures for stops 80 which control the operation of the swinging latch, and one series of apertures for stops for the rotary latch, and one series for stops 85 which govern the work-receiver.

The swinging latch is shown at 331. It is 90 fulcrumed at 332 to the lug on the hood 333, which encircles the stop-carrier 330, as shown in Fig. 26. It projects down past the end of the stop-carrier 330 and is provided with an 95 engaging member or lug 334, adapted to engage the pins 335 in one of the series of apertures. The stops and trip members on the stop-carrier are shown in almost every 100 instance on this machine as consisting of pins dropped removably into apertures in the stop-carrier and held against displacement by the encircling hood 333; but it will be understood that I do not limit myself in any 105 wise to the employment of unthreaded pins thus held removably in place, for I may, if 110 desired, use screws, detachable or adjustable, cams, lugs, or other mechanical equivalents 115 of the pins. Thus while I have termed the pins or cams on the controller "stops" or "trip-pins" or "members," respectively, as a convenient means of designating them, the words are not intended to have a limiting effect, but, on the contrary, to be generic in 120 their meaning.

It should be observed from Figs. 26 and 125 29 that the engaging member 334 has a slightly-inclined face to engage the stop 335, so that the tendency of the member and the stop is to be disengaged by the camming action of the one upon the other. Therefore 130 means must be provided to normally hold the swinging latch 331 in operative position. The means which I provide for this purpose consists of a bell-crank 336, suitably fulcrumed upon a stud 337, secured to the hood 333. The bell-crank is provided at the end of one arm with a finger 338, which engages the free end of the swinging latch 331. The other arm 339 upon the bell-crank is laterally

extended, and inasmuch as the bell-crank is itself located within the periphery of the stop-carrier 330 the arm 339 extends entirely across the intermediate series of apertures 5 for the trip-pins, said series being six in number, as previously stated. There is one series of apertures 340 for each tool on the turret, and for one complete cycle of operations for the lathe I place one pin in each of the six 10 series of apertures in the stop-carrier. These pins are indicated at 341, and they are movable radially relatively to the stop-carrier, being adapted as the stop-carrier is moved progressively to occupy in succession an operative 15 position with respect to the tripping bell-crank 336. These trip-pins 341 do not of themselves cause the operation of the tripping bell-crank, but are struck in turn by a hammer as they reach operative position. 20 This hammer is indicated at 342, being weighted, as at 343. It has a head 344, which is adapted to engage the end of each pin 341, provided the hammer be in proper position to do so. The said hammer is adapted to 25 move not only toward and from the stop-carrier, but also in a direction lateral of its length. The lateral position or location of the hammer is controlled by the turret, which is formed with a series of internal cam-sur- 30 faces 345, as best shown in Fig. 20. There are six of these cam-surfaces, and they are at different distances radially from the axis of rotation of the turret. The lever 346 is fulcrumed upon a stud 347, rising from the 35 carriage, and is equipped with a roll 348, adapted to bear against the cam-surfaces 345 in succession as the turret rotates. The free end of the lever bears against a rod 349, suitably secured in the carriage and arranged lat- 40 erally to the travel thereof. This rod 349 bears at its outer end against an arm 350 on a rock-shaft 351, journaled in the carriage. The said arm is provided with a shoulder 352, so as to normally rest lightly upon a rod or 45 bar 353, supported at its ends by links 354 and 355, as shown in Fig. 19, said links being in turn pivoted to a stationary bar 356, secured to the front of the bed in such way as to permit it to rock, although it is held against lon- 50 gitudinal movement. To the lower end of the link 354 is adjustably secured an arm 357, to which the swinging hammer 342 is pivotally attached, as indicated in Fig. 24, the pivotal attachment being such that when the 55 arm 357 moves in the direction of the arrow in Fig. 24 the head of the hammer will be caused to strike the pin if one be properly located with reference thereto. A spring 999 holds the lever 357 in an inoperative position. 60 The cam-surfaces operating upon the roller of the lever 346 cause the latter to move the pin 349 and through the lever 350 to depress the bar 353, and thereby swing the hammer 342 laterally or across the series of apertures 65 in the stop-carrier, as shown in Fig. 25. Consequently the position of the hammer is controlled directly by the turret, this mechanism

including in its simplest form a swinging member operated by a series of cam-surfaces on the turret adapted to occupy for each position of the turret a predetermined position with respect to the stop-carrier. In order to swing the rock-shaft 353 to cause the hammer to strike against the pin 341, I utilize a portion of the mechanism which operates the index-pin. Referring now to Fig. 34, it will be observed that the rock-shaft 292 is provided with an upturned arm 360, which bears against a rod 361, parallel to that at 349. At its outer end this rod 361 bears directly against a centrally-fulcrumed lever 362, (see Fig. 26,) the lower end of which bears against the bar 353. Consequently when the index-pin is forced by its spring into its bushing 289 the quick action of the spring causes a quick rocking 85 movement of the rock-shaft 292 and through the intermediate parts just described effects a movement of the bar 353 toward the bed and swings the head of the hammer against pin 341, and as the stop-pin is driven inward 90 it engages the arm 339 of the bell-crank 336 and throws the finger 338 out of engagement with the free end of the swinging latch 331, and the controller-shaft is then free to 95 advance another step. The action of this escapement mechanism takes place when the turret has reached its farthest position from the chuck and just as the locking-pin slips into its bushing, and its purpose is to prevent a forward movement of the turret in 100 case the sequence of operations has been disturbed. In other words, if the hammer does not strike the proper pin in the controller or stop-carrier the controller will not be released and the valve mechanism cannot be 105 actuated. By providing for the position of the hammer being controlled by the rotation of the turret the hammer must be in line with the proper pin in order to actuate the latch—that is to say, when the turret is in position for 110 the first tool to operate upon the work then the hammer is in line with the first row of holes, and as the turret rotates step by step successively the hammer is likewise moved successively in line with the second row of 115 holes, then the third, &c., until it reaches a position in line with the sixth row. After the turret has completed one rotation the hammer is moved automatically back in line with the first row of holes on the stop-carrier. 120 *Rotary latch.*—The rotary latch which governs the escapement mechanism is under fluid control, and its use prevents the stop-carrier or controller from moving more than one step at a time, which might happen were a swinging latch or pawl alone used. By reference to Figs. 19 to 24 it will be seen that the rotary latch consists of a spirally-grooved wheel 365, journaled on a pin extending from the top of the hood 333. The axis of this 125 spirally-grooved wheel is transverse to the axis of the controller-shaft, and the stop-pins 366 on the stop-carrier are adapted to enter the spiral grooves and impart a partial rota- 130

tion to the rotary latch—that is, the grooves are so arranged in relation to each other that when a pin is passed through one of them a tooth or space between two grooves is brought into position to arrest the movement of the next succeeding pin. Therefore as each time a stop is released by the rotary latch it leaves said latch in position to prevent the passage of the next stop on the controller means must be provided to partially rotate said latch to release the last-mentioned stop. The mechanism for accomplishing this is controlled by various operative parts of the lathe and includes a conduit containing a column of fluid having at each end a movable member whereby the vibration of one member will be transmitted through the fluid to the member at the other end. This vibration is not dependent upon directly to effect a movement of the rotary latch, but merely to operate a valve mechanism to permit a flow of fluid into the cylinder 367, (see Fig. 22,) thus forcing the piston 368 and the rod 369 outward, the latter carrying a pawl 370, adapted to engage and move the rotary latch. The spring 373 normally holds the piston in inoperative position. Fluid is supplied to said piston through the pipe 374, of which more specific mention will be hereinafter made. It is sufficient at this time to state that in the proper sequence of operations the rotary latch is moved to permit the passage of a stop, thereby allowing the controller-shaft to take one step and cause the actuation of a valve, and thereby cause the next operation of the machine to follow. The cylinder 367 is set at an angle to the axis of the rotary latch, so that the pawl is adapted to engage the tooth of said member and operate the same, as shown in Figs. 20 and 21.

Cutting-off tool.—To obtain an understanding of the construction and operation of the cutting-off tool, reference may be had to Figs. 36 to 61, inclusive. The tool itself may be constructed in any desired way. In the figures noted it is indicated at 376 and is secured in the top of a plunger 377, arranged vertically in the bed of the lathe and adapted to be projected upwardly toward the under side of the work. The lower end of the plunger passes downwardly into the cylinder 378, secured by screws and trunnions 379 to the sides of the bed, as best shown in Figs. 37 and 38. The plunger passes through a stuffing-box 380 and is provided with curved deflectors 381 for the deflection of the oil and chips to an inclined plate 382, which guides them toward the end of the lathe, where the oil may fall into a convenient trap or conduit. This plate 382 extends from side to side of the bed and has an aperture 383, through which the plunger passes. To guide the plunger in its movement, it is provided with a projection 384, which is apertured to receive a guide-bar 385, fixed in lugs 386 and 387, projecting inwardly from one side of the lathe-bed. There is a supplementary guide

388, secured to the casting 254, in which a lug or projection 389 on the plunger slides when the tool reaches cutting or operative position. The fluid-operated mechanism for operating the cutter is so constructed as to advance the cutter rapidly to operative position and to then feed it slowly while it severs the finished work. I employ pneumatic pressure for operating various parts of the lathe and retard the movement of the cutting-off tool by liquid, which I throttle to regulate its flow. The cylinder 378 is cast with a tank or receptacle 390, there being a valve mechanism interposed between the tank and the cylinder for regulating the flow of liquid one from the other. The valve mechanism is contained within the casting 391, which is bolted to the cylinder, as indicated in Figs. 36 and 37. This casting projects through the forward side of the bed near the bottom thereof, as shown in Fig. 1, and not only contains the mechanism for throttling the flow of the fluid, but it contains the automatic mechanism by means of which the pressure on the tool during the feeding operation can be increased in proportion to the increase in resistance offered to the action of the tool by the work. So long as the plunger is rising and before the tool has reached operative position the liquid flows freely from the tank into the cylinder; but the valve is shifted automatically when the tool reaches operative position to cause the liquid to flow through a throttling mechanism. To operate the valve, I provide a vertical rock-shaft 392, which is connected by a spline to the valve-plug 393. (See Figs. 36 and 48.) The upper end of this shaft, which is indicated at 394, is connected telescopically thereto and is provided with a crank-arm 395, to which is attached a connecting-rod 396, projecting into the path of the cam 397 on the projection 384. The connecting-rod 396 is itself vertically adjustable, so that it may be operated at any time during the upward travel of the plunger. When the cam on the plunger engages the pin 396, the rock-shaft 392 is rocked to shift the valve and cause the liquid to pass through the throttle from the tank to the cylinder. The valve mechanism itself is best shown in Figs. 47 to 61, inclusive. The valve-plug 393 is provided with two sets of ports, one controlling the supply of liquid to the cylinder and the other controlling the supply of air to the tank to force the liquid into the cylinder. The conduit for supplying air to the tank is indicated at 400, there being connected therewith a pipe 401, leading from the main air-supply pipe 550. (See Fig. 95.) This conduit is connected to the pipe 402, which leads to the upper portion of the tank, as shown in Fig. 39. The conduits which connect the tank with the cylinder are located at the lower ends thereof and are indicated at 403 and 404, Fig. 49. The valve 393 is provided with ports 405 and 406, respectively located in the planes of the air and liquid con-

duits, respectively. The valve-plug is adapted to be moved to either of three positions. (Indicated in Figs. 51 to 56, inclusive.) In Figs. 52 and 55 the valve-plug is in position to permit air to pass through passage 407 and conduit 400 into the tank and to permit the fluid from the tank to pass through conduits 403 and 404 into the cylinder. The plunger 377 now rises, and when the cam 397 engages the pin 396 the valve-plug is shifted to the position shown in Figs. 51 and 54, by which air is still supplied to the tank; but the direct communication between the conduits 403 and 404 for the liquid is cut off, the liquid now being obliged to pass through the throttling portion of the valve mechanism, as will be described. When, however, the cutting-off tool reaches the upward extreme of its movement, the rotary escapement is released by mechanism to be described, and the valve-plug is shifted to the position shown in Figs. 53 and 56, whereby the liquid is free to pass from the cylinder through the conduits 404 and 403 to the tank, (this being caused by the weight of the piston,) and the air escapes through the conduit 400 to the exhaust 408.

By examining Figs. 49 and 51 it will be observed that at the end of conduit 403 there is a duct 409, communicating with the chamber 410. On one side of the diaphragm 411, which divides the chamber into two compartments, the outer wall of said chamber is formed by a screw-cap 412. The inner compartment of said chamber communicates with conduit 404 by means of a throttle-aperture 413, into which projects a needle-valve 414 on the end of an adjustable valve-stem 415. In the port 409 there is formed a valve-seat for a regulator-valve 416, which is limited in its movement in one direction by the adjustable pin 417. This check-valve operates against a stud 418, secured to the central portion of the diaphragm, there being a strong spring 419 placed in a socket in the cap 412 and bearing against said stud. The tension of the spring 419 may be adjusted by the screw 420. The stud is provided with ports to admit liquid into the inner compartment of the diaphragm-chamber at all times, as shown, and in order for the check-valve to close against its seat the pressure must be great enough to overcome the tension of the spring 419. A spring 421 serves to hold the check-valve against the stem of the stud 418. The outer compartment of the diaphragm-chamber communicates by a port 422 with the conduit 404, leading to the aperture 413. Now it will be observed that when the tool-carrying plunger is rising to the point where the tool is to engage the work and the valve-plug is shifted to the position shown in Fig. 51 the liquid is compelled to travel through the port 409 into the conduit 404. The flow of the liquid is thus reduced in rate, and the tool therefore is fed slowly against the work.

Assuming that there is in port 403 a working pressure of one hundred pounds and in

chamber 410 a pressure of fifty pounds and that the spring 419 is set with a tension of fifty pounds, it will be seen that the pressure-regulator valve 416 will remain open until the pressure against the upper side of the diaphragm in chamber 410 exceeds that of the spring. As soon as the pressure in chamber 410 is reduced by the flow of fluid through the throttle-valve (which is open) into the duct 404 the spring 419 opens the regulator-valve 416, thus keeping the pressure in chamber 410 at fifty pounds as long as the pressure in chamber or duct 404 effects a movement of the piston. As soon as there is a resistance to the passage of fluid through duct 404, (which duct leads to the cylinder,) caused by the resistance of the piston, the pressure in said duct increases, and this pressure is communicated to the spring side of the diaphragm by duct 422 to further open the valve 416, and hence the pressure in the chamber above the diaphragm will be increased directly as the pressure in the chamber under the diaphragm is increased by the opening of said valve 416, so that there is a constant difference of pressure in the chambers of fifty pounds to keep a constant head acting to force liquid through port 413. It should be remembered in this connection that the fluid must flow slowly through the throttle into the duct 404 and that so long as the piston in the cylinder with which such duct connects is free the pressure in the duct will be less than the pressure in the chamber 410. If, for instance, the pressure in duct 404 is, say, ten pounds, the pressure on the spring side of the diaphragm 411 will be increased by ten pounds, so that the combined pressure of the fluid and the spring against the diaphragm will be equal to sixty pounds. Immediately the valve 416 will be raised to admit fluid to the chamber 410 until the pressure therein is sixty pounds, so that the result will be again a net difference in pressure of fifty pounds on the two sides of the throttle 413. Of course the pressure in duct 404 of only ten pounds will not increase the pressure in the chamber 410 so long as the piston is moving, because the fluid is flowing into the duct 404 through the throttle. If, again, the pressure in 404 should increase by the absolute cessation of movement of the piston, then the conditions would be absolutely changed; but in accordance with my invention I propose to always have an excess of pressure in 403 above that required to move the tool. Thus if the resistance of the cutting-off tool is such as to require twenty pounds pressure per square inch this pressure is added to that of the spring 419 to assist in holding the regulator-valve open, thus admitting seventy pounds pressure to the receiving side of the throttle, but yet maintaining a net difference of fifty pounds per square inch between the two sides of the aperture of the throttle. Consequently from this it will appear that the pressure on the receiving side of the throttle will increase

in direct accordance with the increase on the delivery side due to the resistance of the tool against the work.

The arrangement of the main valve for the cutting-off-tool cylinder, the throttle-valve, and the pressure-regulator valve all in one casing greatly simplifies the construction, rendering it compact and convenient in form. Any system of piping, however, which includes a pressure-regulator arrangement to maintain a fixed net difference between the two sides of the throttling device will accomplish the same purpose and would be obviously comprehended in my invention.

15 The exact form of piston which carries the cutting-off tool is not essential to the invention, since it can be a single or double acting piston, suitably held against rotation; but for obvious reasons I have preferred to employ the form of single-acting piston which I have illustrated and depend upon gravity for its return to inoperative position.

The rod 396, which operates the valve-plug 393, is loosely pivoted to the crank 395, as best shown in Figs. 59 and 60, being equipped with a block 430, from which a pin 431 projects downwardly into a slot 432 in said crank-arm. At its outer end the rod 396 is pivoted to a lever 433, secured to a forwardly-projecting casting 434, attached to the front side of the lathe. The rock-shaft 435, to which the lever 433 is secured, is equipped with a handle 436, by which it may be rocked, said handle projecting forwardly to be of convenient access to the operator. (See Fig. 78.) This rock-shaft may not only be moved manually, but may be operated automatically by the controller, as will be subsequently explained. The handle moves in a vertical direction to

40 obtain a corresponding motion of the piston, and vice versa. The normal position of the handle is at its lowest extreme, at which time the valve-plug has cut off the air-supply and opened the exhaust for the air in the tank.

45 The tank therefore is now only full of liquid. In ordinary use the valve-handle is first raised to its upper limit of movement to cause the valve-plug to assume the position shown in Figs. 52 and 55, whereby the air-supply is delivered to the tank and the fluid is permitted to flow unthrottled from the tank to the cylinder. This brings the tool quickly into position to operate upon the work. Then the handle is thrust downward to an intermediate position by the cam 397 engaging the end of the rod 396, and the valve-plug is shifted to the position shown in Figs. 51 and 54. The rapid upward movement of the cutting-off tool is thus quickly retarded, the liquid being now compelled to pass through the throttling-valve and being consequently fed with a slow movement as the tool operates upon the work. As soon as the tool reaches its upward extreme of movement by a mechanism which I shall subsequently describe

65 the rotary escapement for the controller is

actuated to permit the controller to rotate one step and by a stop-pin thereon actuate the plug-valve and move it to the position shown in Figs. 53 and 56 to permit the air to 70 exhaust from the tank and the liquid to pass from the cylinder into the tank as the plunger or piston settles downward by its own weight.

In order to effect the operation of the escapement, I employ a column of fluid such as heretofore briefly referred to, and I provide means whereby the piston or plunger for the tool-carrier imparts a motion to the member at one end of said column. 75 8c

Referring to Fig. 44, 437 indicates a casing containing a diaphragm, as will be described in detail. A pin 438 bears yieldingly against the diaphragm and projects through the front of the lathe-bed in position to be engaged by 85 an arm 439. This arm projects laterally from a rock-shaft 440, journaled in the lugs 386 and 387, as shown in Fig. 38. The said shaft is held from rising by a small screw 441. (See Fig. 41.) On the said rock-shaft are 90 two small clips 442 and 443 in position to be engaged by a lug 444 on the plunger 377 and said clips being so constructed as to slightly rock the shaft 440 when they are engaged. The clips 442 and 443 are located, respectively, at the upper and lower extremes of the travel of the plunger, so that when the plunger reaches the end of its movement in either direction the shaft is rocked and the arm 439 carries the pin 438 outward or into 95 the diaphragm-casing with a quick impulse or movement. This impulse is transmitted by a column of fluid to the rotary escapement to release the controller and permit it to advance one step. 105

Tool-closer and mechanism for operating the same.—I provide in this machine for the employment of tools on the turret which may be automatically closed when the tool reaches a predetermined point in its travel toward 110 the chuck and also to use in conjunction therewith a tool-closing bar substantially as illustrated and described in said Patent No. 672,398, although it will be seen from the following description that I have devised an 115 improved fluid-controlled means for operating said closer-bar, said means being controlled either manually or automatically. The closer-bar itself is indicated at 445. (See Figs. 1, 2, 4, and 62.) It is secured in a support 446 in the form of an elongated bar mounted at its ends in two end bars 447 and 448, fulcrumed upon pivot-studs 449 and 450, respectively. The pivot-stud 450 is secured in the housing 451, which encircles the chuck 120 of the driving-spindle, whereas the stud 449 is secured to a support 452. (Best shown in Fig. 2.) The bar 446, together with the two end bars 447 and 448, constitute a rocking or swinging frame, whereby the movement of 125 130 the closer-bar 445 is substantially vertical, the said frame being so located that the

closer-bar will be located directly above the closing member of the operating-tool on the turret.

The tool-closer bar is held normally raised, 5 so that the tools on the turret are free to move relatively thereto without engaging it, and the bar may be depressed at any point in the travel of the turret without affecting the operation of the latter.

10 To operate the frame and depress the closer-bar, I employ a cylinder 453 at the end of the bed farthest from the chuck and having a suitable piston with a piston-rod 454 attached to the end bar 447, as shown in Figs. 5 2 and 4, where it is out of the way of the operator. Fluid is admitted to the cylinder by two conduits or pipes 461 and 462, (see Fig. 95,) the supply of fluid to which is controlled by a valve. (Indicated as a whole in Figs. 20 78 and 79 as 457.)

The valve is adapted, as heretofore stated, to be operated either manually or automatically, as indicated in Figs. 78 and 85 to 91. I do not use liquid in the operation of the 25 tool-closer bar, as the evenness of the movement of said bar is not material, it being necessary merely to move it from one extreme to the other. The valve-plug, as shown at 458, is equipped with a handle 459, by which it 30 may be operated. The fluid-supply conduit is indicated at 460. The pipe leading to the upper end of the cylinder is indicated at 461 and that leading to the lower end of the cylinder at 462.

35 When the handle is raised, the plug is shifted to permit the flow of fluid from inlet 460 through pipe 461 to the bottom of the cylinder, there being now a communication between the pipe 462 from the top end of the 40 cylinder and the exhaust 463, as shown in Fig. 88. When the handle is thrust downwardly, the plug is shifted to the position in Fig. 89, which shows the fluid as passing from the inlet 460 to the pipe 462 to the upper end of 45 the cylinder and with the exhaust from the cylinder passing from a pipe 461 to the exhaust-duct 463. The automatic mechanism for operating the valve I will hereinafter set forth.

50 *The work-receiver.*—The work-receiver is somewhat similar to that illustrated in my said patent. It includes two hook-shaped arms 466 466, pivoted to two supports 467 467, secured to a rock-shaft 468. (See Figs. 36, 55 37, and 62, which may be taken in connection with Figs. 1, 2, and 4.) This shaft 468 is journaled in the end bars 447 and 448 of the frame which supports the tool-closer. On its end it is equipped with a gear-segment 469, 60 intermeshed with another segment 470, fulcrumed on a stud 471, projecting from the end bar 447. (See Fig. 4.) The segment 470 is connected by a rod 472 with bell-crank 473, fulcrumed at 474 at the end of the lathe, as 65 best shown in Fig. 62. One of the arms of the bell-crank to which the rod 472 is at-

tached projects at a slight inclination from the horizontal, while the other arm extends upwardly at an inclination to the vertical.

The rocking bar or shaft 475 is journaled at one end in a block 476, attached to the shorter arm of the bell-crank and at the other end in a similar block 477 on the oscillatory support 478, fulcrumed at 4781 to the rear of the lathe-bed. The arm or support 478 is 75 substantially parallel to the shorter arm of the bell-crank 473, so that the said rock-shaft 475 may not only be moved about its axis, but may be moved bodily longitudinally. In order to rock the shaft, it is provided with a 80 lug 479, projecting downwardly therefrom to be engaged by the head 480 of a rod 481, projecting downwardly and forwardly through the bed, as shown in Fig. 2, and resting against the pendent or swinging arm 482, pivotally 85 supported at 483 to a lug 484, projecting forward from the front of the lathe. This arm has a cam-lug 485, adapted to be engaged by a stop on the controller. At the proper time the rod 481 is moved rearwardly and the shaft 90 475 is rocked. The purpose of this rocking will now be explained.

A collar 486 is adjustably secured to the shaft 475, and it has a finger 487, which is normally out of the path of a notched plate 95 488, secured to the turret-carriage, as shown in Fig. 62. This plate has two downwardly-extending projections 489 490, which form the notch, and under normal conditions the turret-carriage is free to slide back and forth 100 without either of said projections engaging the finger 487, the latter being in position shown in Fig. 62. When the shaft 475 is rocked, however, the finger 487 is moved into the path of the projection 490 on account of 105 the latter being longer than that at 489. As the carriage moves rearward after the last operation upon the work the projection 490 engages the finger 487 and moves the bar 475 longitudinally away from the chuck. This 110 swings the bell-crank 473 about its fulcrum, draws downward the rod 472, and through the medium of the gear-segments rocks the shaft 468 to swing the hook-shaped arms under the work. When the work is severed, it 115 drops into said arms, and the next time the carriage moves forward the projection 489, engaging the finger 487, swings the bar 475 toward the chuck to move the work-receiver 120 rearward out of the way of the tools on the turret. As the hooked arms swing rearwardly the work is discharged therefrom by a finger 491 on one of the arms engaging a pin 492 on the end bar 448, as shown in Fig. 3. It is to this end that the hooked arms are 125 loosely pivoted to the supports which project forward from the rock-shaft 468.

In order to permit the controller to turn at the proper time to effect the rocking of the shaft 475, the controller must be in perfect position for the cam projection 485 to rest upon the stop with which it is engaged. There is

only one stop to accomplish this, as the work-receiver is only operated once during each complete cycle of operations of the lathe.

Mechanism for controlling the stock feed.—

I have heretofore described the chuck opening and closing mechanism and the device which controls the roller-feed for the stock. I shall now describe briefly the mechanism by which the escapement is controlled to permit partial rotation of the controller-shaft to close the chuck and render the roller-feed inoperative. This mechanism is substantially similar in many respects to the one illustrated in my said patent. It consists of an arm 493, secured to the rock-shaft 468, as shown. When said shaft is rocked to swing the work-receiver under the finished stock, the end of the arm 493 is moved toward the axis of the work. A spring-held stop 494 is pivoted onto the arm, and as soon as the severed work drops the stop swings up into position to be engaged by the end of the stock, when the bar is fed forward by the roller-feed. The shaft 468 has a slight longitudinal movement, being held toward the chuck by spring action. The said shaft carries an adjustable lug 498, which when said shaft is rocked is brought into alignment with a pin 499 in a diaphragm-casing 500, supported by the end bar 447 of the tool-closer-bar frame.

When the stock is being fed by the roller-feed and engages the stop 494, the bar 468 moves longitudinally and the lug 498 engages the pin 499 and imparts an impulse to the diaphragm in the casing 500. Through the medium of the fluid connection the rotary escapement is moved to permit the controller to rotate one step and shift the valve mechanism, so as to close the chuck and render the roller-feed inoperative.

*The fluid communication between the rotary latch and the various operative parts of the lathe.—*As has been outlined, the rotary latch is controlled by a column of fluid, through which an impulse or vibration can be imparted from one member to another member. In Figs. 94 and 95 I have illustrated somewhat diagrammatically this fluid communication, and reference may now be had to said figures.

It will be remembered that the rotary latch is actuated by a fluid-operated piston and cylinder and that the pipe 374 admits fluid thereto from a supply-pipe 503. This is shown in Figs. 94 to 97. Between the two pipes, however, there is placed a valve 504, located in a diaphragm-casing 505 and held against its seat by a spring 506. Said valve is connected to a diaphragm 507, placed in said casing, said diaphragm serving as a movable member at one end of the column of fluid. The spring 506 is strong enough to hold the valve 504 normally closed against the pressure of the diaphragm 507. The pipe 508 leads to the opposite side of the diaphragm, and when fluid is admitted to said side of dia-

phragm the valve 504 is opened long enough to admit the fluid to the cylinder 367 and effect a movement of the piston 369 sufficient to impart a partial rotation to the rotary latch and move it out of the path of one of the stops on the escapement to permit the controller to advance one step.

Connected with the diaphragm-casing 505 and with the pipe 508 there are branch pipes 509 and 510, the latter having two branches 511 and 512. The pipe 509 leads to the diaphragm-casing 437, in which the diaphragm is operated meditately by the plunger for the cut-off tool. Branch pipe 511 leads to the diaphragm-casing 513, (see Figs. 94 and 95,) carried by the turret-carriage, while the branch pipe 512 leads to the diaphragm-casing 500, to the diaphragm of which an impulse is given by the shaft 468.

With the exception of the diaphragm shown in Fig. 97 the other diaphragms are substantially similar, so that I shall describe only one of them—to wit, that one which is indicated as a whole at 513 and is shown in Fig. 72. The casing is formed in two parts, with the diaphragm 514 between them. The pin 515 bears against one side of the diaphragm, while a spring 516 bears against the other side to hold said diaphragm in a neutral position. The pin 515 is formed with a head 517, between which and the pin 1305 is placed a compression-spring 518. The compartment on the spring side of the diaphragm communicates with a conduit which leads to the compartment 520 of the diaphragm 505, (see Fig. 97,) and said conduits are completely filled with fluid and preferably liquid. The flow of the liquid from the compartment on the spring side of the diaphragm, except that shown in Fig. 97, is controlled by throttle-valve 521. Now it will be seen that when any one of the pins 1305, 438, or 499 is engaged and thrust inward the liquid will be forced through the spring side of the corresponding diaphragm-casing and the diaphragm 507, Fig. 97, will be forced against pressure of spring 506 to open the valve 504 and permit the flow of fluid into the actuating-cylinder for the rotary latch. This means by which fluid control of the rotary escapement is effected greatly simplifies the machine and reduces to a minimum the number of operative parts. The conduits which connect the various diaphragm-casings may be in the form of hose wherever necessary, particularly where one of the diaphragms is necessarily mounted upon the movable part of the lathe, as on the turret-carriage.

The location of the diaphragm-casing is immaterial, provided the escapement is actuated at the proper time and in the proper sequence. The provision of the compression-spring between the diaphragm and the actuating-pin provides for cushioning the stroke of the pin and permitting proper allowance of lost motion between the operating part which comes in contact with the pin and the

diaphragm. I can also operate the escape-piston by the medium of the diaphragms located at various other parts of the machine and actuated by various movable elements.

- 5 As shown, the rotary latch is actuated by the transmission of an impulse from one diaphragm to the other when the stock has been fed a proper distance by the roller-feed, when the tool-carriage has reached its limit of 10 movement toward the chuck, and when the cutting-off tool reaches its highest and lowest extremes of movement, respectively.

Valve mechanism for turret-carriage, feeding-cylinder, and the regulator mechanism.—

- 15 For convenience in construction and operation the valve for controlling the supply of liquid to the carriage-feeding cylinder and the passage of the liquid to the regulator mechanism are all contained in one casting and 20 bolted to a liquid-tank at one end of the bed.

It has been my object, as stated in the beginning of this specification, to employ liquid on both sides of the piston in the carriage-operating cylinder and to prevent the trapping 25 and accumulation of air or gas in the conduits, and therefore I have provided a tank 529, having two separate compartments or chambers 530 531, one adapted to be connected by a conduit with one end of the carriage-

- 30 feeding cylinder and the other by another conduit to the other end of said cylinder, which tank is located considerably above the plane of the carriage-feeding cylinder, as indicated in Fig. 2, and supported upon the 35 bed or frame of the machine and to the under side of which the valve-casing 532 is secured. In this casing is a valve-plug 533, to which is attached at one end an arm 534, connected by a rod 535 with a lever 536, secured 40 to a rock-shaft 537. (See Fig. 78.) This shaft has a handle 538, which may be rotated; but it is also adapted to be operated by stops on the controller. The valve-plug 533 is shown in detail in Figs. 103 to 112. It controls 45 the supply of air to either of the chambers 530 531 of the tank, the passage of liquid from said compartments to the ends of the operating-cylinder, and also controls the passage of liquid through the regulator or 50 meter. It is located in a tapering aperture 539 in the casing 532. The ports leading the liquid from the chambers 530 531 to the valve are indicated at 540 541, respectively.

The chuck end of the operating-cylinder is 55 connected by the end 542 of pipe 259 with a port 543, leading into the valve-casing 532, the opposite end of said cylinder being connected by the end 544 of pipe 258 with the port 545. When the valve-plug 533 occupies 60 its usual position, as shown in Fig. 106, at which time the handle 538 occupies the central position, as shown in Fig. 78, the flow of liquid from both chambers is cut off. The valve, however, may be shifted to the position shown in Fig. 104, in which direct communication is effected between the ports 540 and 545 and the ports 541 and 543. This will

70 permit the liquid to flow freely from one compartment into one end of the cylinder and from the other end of the cylinder into the other compartment and depending upon the compartment into which the pressure of air is directed.

The valve is moved into the position shown in Fig. 104 when it is desired to move the carriage rapidly; but in order to feed the carriage slowly when the tool thereon is operating on the work I employ a meter or regulator and deflect the liquid therethrough. Said meter, however, will be described subsequently, it being sufficient to state at this time that fluid is adapted to pass to said meter through a port 546, (see Fig. 103,) with which either one of the ports 540 541 is adapted to communicate. When the liquid leaves 80 the meter, it passes through the port 547 (see Figs. 116 and 118) and is adapted to be deflected by the valve to either of the ports 543 545, which communicate with pipes 548 549, respectively. (See Fig. 111.) When the 85 valve-plug is rocked to cut off the direct communication between the chamber in the tank and the cylinder—as, for instance, in Fig. 103—to cause the liquid to pass through the regulator or meter, the said valve permits 90 free communication between the exhaust from said meter and the pipe or port leading to the cylinder.

The main air-supply pipe is indicated at 95 550, and its branch 551 (see Figs. 94 and 95) connects with a port 552. (See Fig. 108.) The plug is so formed that the air can be deflected into either of two conduits or ports 553 554 or to an exhaust-port 555. With the ports 553 and 554 communicate two upright 100 pipes 556 and 557, respectively, which project upwardly into the two chambers 530 531 and end near the upper walls of the same for the purpose of discharging the air into the top of each chamber. When the valve occupies a 105 neutral position, with the handle 538 in position shown in Fig. 78, the air-supply through the conduit 551 is cut off, and the gases generated in the liquid in the tank may exhaust 110 through the port 555, as shown in Fig. 109.

115 It is unnecessary to describe in great detail the construction of the valve and plug, as the latter is clearly shown in the various figures, it being sufficient to state that it has three cavities 558, 559, and 560, which control the passage of the liquid from the tank to the regulator, two cavities 561 and 562 in another plane for controlling the passage of the air to the tank-chambers, and a single cavity 563, which controls the passage of liquid 120 from the meter or regulator to the feeding-cylinder. Between the cavities for the liquid and those for the air the valve has a circumferential groove 564, communicating 125 with the discharge-duct (not shown) for preventing the access of air to the meter or regulator. The handle 538, which controls the movement of the plug, is adapted to occupy 130 any one of the seven different positions, and

it is provided with an indicator or pointer 565, which swings along a graduated scale 566, the gradations of which are symbolized to indicate the various positions of the valve. When it is desired to move the carriage to the left or toward the chuck, the handle 538 is moved to the left, and vice versa.

The pipes which connect the valve mechanism with the feeding-cylinder are shown 10 diagrammatically in Fig. 94 as substantially horizontal. Nevertheless I prefer that they should be at a slight incline, so as to rise gradually from the feeding-cylinder to said valve-casing. The meter or regulator by 15 which the flow of the liquid to the feeding-cylinder is controlled or retarded is shown in Figs. 113 to 119. The valve-casing 532 is formed with a threaded boss 567, to which is secured the hollow extension 568. Journalized 20 in the latter is a shaft 569, passing through the stuffing-box 570 and having on its end a belt-pulley 571, connected by a belt 572 with a pulley or belt wheel 573 on the spindle of the lathe. The shaft is thus rotated continuously 25 as long as the lathe is in operation. In the hollow portion of the extension is a hollow disk valve 574, having its stem 575 located in an eccentric socket in the head 576 of the shaft 569. This valve is held against 30 the face of the boss 567 by a spring 577.

The cavity 578 in the disk valve communicates at all times with a port 579, leading into the port or duct 547, this port being located with its mouth in the center of the face of 35 the boss, as shown in Fig. 119. Located outside of the travel of the disk valve 574 is the mouth of the duct 580, which from Fig. 103 will be seen to communicate with the duct 546. Liquid therefore flows from the ducts 40 546 580 into the interior of the regulator-casing 568 and holds the valve 574 against its seat, this being assisted by the pressure of the spring 577. Arranged in a circle about the port 579 are the mouths of four ducts 45 581, 582, 583, and 584. The ducts 581 and 583 communicate with the opposite ends of a cylinder 586, while those at 582 and 584 communicate with the opposite ends of the cylinder 585. In the two cylinders are two loose 50 pistons 587 588, respectively, which are adapted to measure off the charges of liquid to the carriage-feeding cylinder. Each of the pistons has a differential movement according to the position of the piston-pin 589, projecting into the cylinder through the stuffing-box 590. The mechanism for adjusting these pins will subsequently be explained. As 55 the disk valve 544 swings around in a circle it connects each of the ducts 581 582 583 584 first with the inlet-port 580 and then with the outlet-port 579, this being illustrated and described in my Patent No. 700,644, dated May 20, 1902, to which reference may be had for a more complete understanding thereof.

When the liquid is admitted into one end 60 of the cylinder 585, for instance, the loose piston is moved in the opposite direction and

the liquid in front of it is forced outward from the duct 579 into the feeding-cylinder, and when liquid is introduced into the other 70 end the charge of liquid previously introduced is upon the reverse movement of the piston forced into the cylinder. Consequently so long as the plug-valve is in the upper position and the shaft 569 continues to rotate the 75 liquid is fed in small charges from the tank to the cylinder, the position of the plug-valve determining which end of the cylinder the liquid enters. This metering or regulating of the liquid insures a comparatively 80 steady and even movement of the turret-carriage; but in order to overcome still further the liability of the carriage to jump after a resistance has been overcome I employ a cushioning device, which is connected to each 85 of the pipes leading to the carriage-feeding cylinder, indicated as a whole at 591 and 592, respectively. (See Figs. 99 and 120.) This cushioning device communicates with a pipe attached thereto by a coupling 593 and consists of the casing 594, having a diaphragm 595, to which is secured a pin 596, slidably held in a threaded sleeve 597, projecting from the casing. The outer end of the sleeve is closed by a screw 598, between which and the 95 pin there is a spring 599, the tension of which may be adjusted by said screw. The sleeve itself is adjustable and is provided with a shoulder for limiting the vibration of the diaphragm. The spring-tension can be adjusted 100 during the operation of the machine so that it has just spring enough to cause a continuous flow of liquid during the interval between the reciprocations of either of the pistons 587 588 of the meter and at the same time weak 105 enough to yield under the hammering effect of said charge. The adjustment of the vibration of the diaphragm which determines the extent of its yielding is generally set to permit the diaphragm to yield from one-half to 110 the full amount of each charge of liquid.

As previously stated, in no case can the turret be caused to jump a distance greater than it would be moved by a charge from either of the cylinders 585 and 586.

The meter in this instance varies from the one shown in my Letters Patent No. 635,888, dated October 31, 1899, or that shown in my Letters Patent No. 672,398 in that I employ a slide-valve instead of a balance-valve, and consequently the liquid flowing through the meter or regulator must always flow in the same direction in order to hold the valve against its seat. Consequently to accomplish this purpose the controlling-valve governs 125 three instead of two sets of ports and conduits, as herein explained.

In my previous meter or regulator liquid was at all times free to flow into the meter from the main pipe and the said meter served 130 as a by-pass around the main valve whenever the pressure caused the liquid to flow in either direction. The turning on of the air-pressure was all that was necessary to cause

the meter to measure off the liquid, whereas the high speed of the feeding-cylinder was effected by opening the main liquid-valve, which permitted the liquid to flow into the 5 cylinder without passing through the meter, although the passage through the meter remained open. In the present instance the first slight turn in either direction from a neutral position connects the air-pipe with 10 the tanks, but also cuts off the passage of liquid directly from the tank to the cylinder and sends it through the meter to the cylinder. A further turn of the valve in either direction opens direct communication between the 15 tank and the cylinder. The differential movement of the meter-pistons is effected or controlled by the controller. The cylindrical support 328, hereinbefore referred to is provided with a series of holes or apertures for 20 the reception of screw-pins, which are adjustable radially of the said support. The screws are indicated at 600, as shown in Fig. 98. In Fig. 99 the apertures 601 for the screw-pins are unfilled. There are as many of these pins 25 as may be necessary to vary the movement of the turret-carriage, said pins pressing in succession against the flat end 602 of a lever 603, fulcrumed at 604 and having a flat upper end 605, which bears against both the piston-pins 30 589. These pins are pressed outwardly against the flat end 605 of the lever by the internal pressure in the cylinders 585 586. This mechanism is the simplest form for controlling the movement of the loose pistons. 35 The lever 603 must be bent to one side, as shown in Fig. 99, to bring its end 605 in alignment with the piston-pins.

Valve mechanism for the operative parts of the lathe.—I have hereinbefore stated that 40 practically all of the parts of this lathe may be governed in their movements either automatically or manually, and I provide means for easily converting the lathe from the condition where it is operated automatically to 45 one in which it is operated manually.

Examining now Figs. 78 and 75, it will be observed that the handle 606, which governs the belt-shipper valve, is connected to the valve-plug 607, to which is secured the arm 50 273, hereinbefore referred to. The handle 608 for the chuck opening and closing valve is connected to the valve-plug 609, (see Fig. 75,) the two handles being arranged side by side, since the two valves are placed upon the same 55 casting and are bolted to a bracket in the front of the bed.

The handle 459 for the valve, which controls the tool-closing mechanism, is arranged next the handle 608. (See Fig. 78.) The 60 handle 436 for the mechanism for operating the cut-off tool is next in line, after which is placed the handle 538, which governs the turret-feeding mechanism. The handles 606, 608, and 538 are arranged to move in a horizontal plane in the direction in which the parts which they govern—to wit, the belt-shipper, the chuck opening and closing mem-

ber, and the turret-carriage all move—whereas the handles 459 and 436 for the tool-closer and the mechanism for operating the cutting-off tool are arranged to move vertically in the direction of movement thereof. Again, it will be noticed that the handles 606, 608, and 538 are advanced in front of those at 459 and 436, where they are of convenient access to the operator. 75

The main air-supply pipe 550 has a branch duct 610, (see Fig. 79,) which supplies pressure to the belt-shipper and chuck opening and closing and the tool-closing cylinders. 80 For the belt-shipper the air passes through either of the ports 264 265, connected with the pipes bearing the same numbers, as heretofore described. For the chuck opening and closing cylinder 241 conduits 611 and 612 lead 85 from the valve-casing to the cylinder. (Indicated in Figs. 79 and 85.) In both of these valves the air is supplied from a branch 610 through the ports 613 and 614, respectively. In Fig. 82 I have shown the valve-plug 607, 90 having on its lower end a splined sleeve 615, secured in place by a nut 616. Surrounding the sleeve is a collar 617, which is adapted to be detachably connected to said sleeve by a latch-pin 618, held in either of two positions 95 by a spring-pressed pin 619. The latch 618 may be forced into and out of engagement with the sleeve, so as to connect the collar thereto or disconnect it therefrom. To the collar are attached two cam-shaped lugs 620 100 621, adapted to be engaged by stops on the controller for the purpose of shifting the valve-plug 607. The valve-plug 609 is equipped with a similar collar 622 and with cam-lugs 623 624, whereby it may be operated either 105 manually or automatically. It also has a pin 800, which bears against a circular spring 801, held in place by a post 802. The purpose of the spring is to return the valve for the chuck opening and closing cylinder to 110 neutral position, so that there will be no strain on the chuck.

The plug 458 for the tool-closing valve is attached at one end to the handle 459, as said, and on its other end is splined a sleeve 625, 115 with a loose collar 626. A latch-pin 627, similar to that previously described, is employed to connect the collar and the plug when necessary. The collar is provided with two cam-lugs 628 629. Inasmuch as it is necessary for 120 the collar to be moved at times in a direction opposite to the peripheral direction of the controller, I interpose between one of the lugs and the controller an arm 630, fulcrumed at 631 to a lug 632, projecting forward from the 125 valve-casing 457. This arm when engaged by the stop-pin swings upward, and by its engagement with lug 628 shifts the valve to an upright position, as shown in Fig. 87, to permit the flow of fluid through duct 462 to 130 raise the tool-closer. This oscillatory movement of the collar brings the lug 629 into a position to be engaged by the same stop which previously engaged the arm 630.

In order to rock the shaft 435, which is connected by a rod 396 with the stem of the valve for controlling the cutting-off tool, it is provided with a similar collar 633, detachably secured thereto by latch-pin 634, having two cam-lugs 635 and 636. (See Figs. 57, 58, 92, and 93.) The lug 635 is swung upwardly by an arm 836, whereas the lug 636 is engaged by the stop on the controller. It should be observed that the cam-lugs 636 and 629 project outwardly beyond the ends of the cam-lugs 635 and 628, so that I may employ two series of stops for each pair of cam-lugs on one of the collars.

15 *The stop-supports on the controller-shaft.*—The cylindrical support 329 on the controller-shaft, which is in operative position with respect to all of the valve-operating ports, is provided with a plurality of apertures arranged in series, of which there are ten in number. There are two series of apertures for the stops which operate each of the valves. These series of apertures are indicated as follows: 637 and 638 for the belt-shipper valve, 639 and 640 for the chuck opening and closing valve, 641 and 642 for the tool-closing valve, 643 and 644 for the valve for the cutting-off tool, 645 and 646 for the valve for the carriage-feeding cylinder. These apertures are not only arranged in series circumferentially of the controller, but they are arranged substantially in rows axially of the cylindrical support. Each series of apertures is indicated by a letter of the alphabet—for instance, as A, B, C, D, E, F, G, H, I, and J. The apertures of each series are numbered consecutively, beginning with the numeral 1. Consequently each aperture for the stop may be designated as A', B', C', &c. The stop-pings are dropped removably into the various apertures in proper position to operate the valves in predetermined sequence and are held from dropping out of the cylindrical support by a hood 647, as indicated in Fig. 1 and also in Fig. 74; but it is within the province of my invention to employ screw-pins, cam-lugs, or other contrivances which may be located in distinct predetermined locations, the record of which may be made. This 50 I regard as an important feature of my invention, for so far as I am aware it has never been possible after manufacturing a certain piece of work upon a turret-lathe to record the positions of the stops on the controller so as to again adjust the machine to reproduce the same piece of work without great study and inconvenience. By the means which I have devised, however, a workman can place the stops in the controller by referring to the record in a few moments.

The apertures in the cylindrical support which forms a part of the escapement are likewise similarly lettered and numbered. There are nine series of apertures on the cylindrical support 330, six for the pins which are actuated by the hammer to trip the spring-latch, one to engage the latch itself, and one

series for the stops which control the operation of the work-receiver and the arm which regulates the feed of the stock, and one for the rotary latch. These series may be indicated as K, L, M, N, O, P, Q, R, and S and the apertures in each series 1 2 3, *et seq.*, whereby the position of these stops may be recorded.

I do not claim herein the stops and the stop-carriers having a plurality of locations for each stop, whereby the locations for a predetermined number of stops may be recorded for the reproduction of a piece of work.

20 *The swinging tray and stop-bars for effecting the feed of the turret-carriage.*—This mechanism, which is distinct in its specific functions from the stop mechanism comprising the stop-bars 297 and dogs 298, does not differ materially from that illustrated in my Letters Patent No. 672,398. The tray itself is indicated at 650, (see Fig. 1,) and it has an extension 651 to engage the lever 536 of the rock-shaft 537 for controlling the valve for the turret-feeding cylinder. It is supported upon swinging arms 652 652, pivotally connected to lugs 653 and fulcrumed at 654 to the bed. The arms are held upright by a spring-pressed device, as shown in Fig. 55 of my last-mentioned Letters Patent No. 672,398. In the tray are placed a plurality of stop-bars 655, separated by spacers or narrow strips of metal 656. Screws 657, passed into the front wall of the tray, bind the stop-bars and spacers all together against movement, the frictional engagement of the bars and spacers being sufficient to prevent any one of them from moving longitudinally. Each bar is provided with a stop 658, which is beveled at 659 and which may be engaged by a spring-pressed pin 660. (See Fig. 31.) This pin is mounted in the hollow end of the depending bar 661, rigidly secured to the slide 349, hereinbefore referred to in connection with the swinging latch. As the sliding bar 349 is moved back and forth by the roller 348, (see Figs. 20, 34, and 26,) engaging the cam-surfaces 345 on the turret, the bar 661 is located over one or the other of the stop-bars 655, of which there are as many as there are tools on the turret or provisions for tools. Of course it is apparent to those skilled in the art to which this invention relates that the turret-carriage must be fed forward for some tools farther than for others prior to the action of the tool upon the work, and therefore I provide for an independent adjustment of the stop-bars. The bar 661 and the pin 660 are advanced step by step across the bed 650, and said pin engages the stops 658 of said bars successively. The bar 661 is held from swinging longitudinally of the stop-bars by being passed down through a slot 662 in an inwardly-projecting web 663 of the overhanging portion of the carriage. When the pin 660 engages one of the stops 659, the tray moves longitudinally and downward, and the extension 651 upon the end thereof engages the arm

25 30 35 40 45 50 55 60 65 70 75 80 85 90 95 100 105 110 115 120 125 130

536 of the valve mechanism and turns it in position to cause the liquid to be deflected through the meter, whereupon the travel of the turret-carriage will be changed from fast 5 to slow and will so continue until the turret reaches the end of its travel, whereupon through the fluid connection between the dogs on the carriage and the rotary escape-ment-latch the controller would be allowed 10 to rotate one step and shift the valve suffi-ciently to cause the turret to recede. I may use this same arrangement of stops and turret-controlled member for limiting the for-ward feed of the turret-carriage in lieu of the 15 dogs and stops hereinbefore described.

Templet-controlled turner.—I have in the preamble to this specification referred to my novel means for dissipating the heat generated by the frictional engagement of the tool 20 with the work and have stated that by the provision of such means I am enabled to use a templet-controlled turning-tool or turner; but before describing the refrigerating or heat-dissipating mechanism I shall describe 25 the said turner. Referring now to Figs. 4 and 129 to 138, the said tool consists of a base-plate 670, secured by screws 671 671 to the turret 202, the location of this and other tools being determined by radial grooves 672 on 30 the flat top of said turret. A standard 673 rises from the base-plate and is equipped with lugs 674 674, and in the base-plate are mounted two stud-shafts 675 675. On each of said stud-shafts there is a sleeve 676, having a for-wardly-projecting arm 677 677. On one of 35 said arms is journaled a roll 678, (see Figs. 130 and 131,) whose peripheral movement is in the direction of the axis of the stock. In the other of said arms is secured the cutter 679, 40 which may be adjusted by a screw 680 and secured after adjustment by a set-screw 681. The said sleeves are likewise provided with two arms 682 682, between which is placed a strong contraction-spring 683, having its ends 45 secured to said arms in any suitable way. Between the arms the standard is provided with a lug 684, having a transverse pivot 685, on which is fulcrumed a triangular wedge 686, whose inclined sides 687 bear against inclined 50 faces on the arms 682 682, as clearly illus-trated. Journaled in this triangular wedge upon a stud 688 is a roller - back rest 689, which is adapted to rotate upon an axis sub-stantially parallel to the axis of the work. A 55 spring 690 tends to hold the wedge firmly in engagement with the inclined cam-surfaces of the laterally-swinging arms 682, with which the arms 677, carrying the roll 678 and the cutter 679, move in unison. The outward 60 edge of the cutter is arranged substantially diametrically opposite the point of engage-ment between the roll 678 and the stock or work 691, whereas the roll 689 is at a point substantially midway between them. The 65 work rotates in the direction of the arrow in Fig. 131, and the resistance, therefore, is up-ward and laterally away from the cutting

edge. By swinging the sleeves 676 so that the arms 677 move toward and from each other, the roll 689 is moved to a similar ex-70 tent toward or from the axis of the work, so that all three of the points 679, 689, and 678 bear with an equal pressure against the work and hold it against lateral or transverse dis-location. The templet, which may consist 75 of a facsimile of the work to be produced, is indicated in Fig. 138 at 692. It is centered by two pins 693 694, projecting in opposite di-rections, one carried by the end bar 448 of the tool-closing frame and the other pin by a 80 bar 695, rigidly secured to the shaft 446. The same mechanism which is employed to rock the shaft to bring the tool-closer into opera-tion is used to move the templet downward 85 into operative position at the proper time. The bars 695 and 448 are connected at their ends by an external templet 696, of which there is a duplicate 697, secured in a groove 90 in the shaft 446, any means being utilized for holding the last-mentioned pair of templets 95 in place. On the upper ends of the arms 682 are two rolls 698 699, which are adapted to move between the interior templet 692 and the exterior templets 696 and 697. As the rolls ride along the templets the arms 682 95 are rocked toward and from each other to ad-just the cutter 679 and the roller-top back rests 689 678 simultaneously toward and from the axis of the work. This turner, as shown, 100 is used mostly for roughing cuts on shoulder-work; but it may be equally well used for finishing all kinds of work in which there are no abrupt shoulders. It has other advantages over various other forms of turners, one of 105 which is its compactness, for it will be seen that it occupies a comparatively small space on the turret. The characteristic difference in construction between this and other turn-ers is in the fact that its cutter-holder and 110 back - rest holder are pivoted on axes sub-stantially at right angles to the axis of the work instead of parallel thereto, and this pre-sents numerous advantages which will be ap-parent to those familiar with the use of lathes.

Instead of the cylindrical cutter I may em-115 ploy a rotary cutter, as shown in my Letters Patent No. 543,551, dated July 30, 1895.

One of the advantages of the cylindrical cutter which I use is the ease with which it may be adjusted. By reference to Fig. 136 120 it will be seen that the cutter is formed in two parts, one of which carries the cutting edge and the other of which—to wit, that in-dicated at 1698—is provided with a lug 1699 to receive an adjusting - screw 700, bearing 125 against the arm 677. The portion 1698 of the cutter is provided with a plurality of aper-tures 701, any one of which may be brought into alinement with one of a lesser number of apertures 702 in the other portion of the cut-ter, so that a pin 703 may be thrust through both of them. This provides a very fine ad-justment when used in connection with the 130 adjusting-screw 700.

Under normal conditions when the turner is not in use the templet is elevated above the turret, where it does not interfere with the use of the other tools thereon.

5 I do not herein claim the construction of the turner *per se*, as it forms the subject-matter of an application, Serial No. 82,551, filed November 16, 1901.

10 *Heat-dissipating apparatus.*—Referring now to Figs. 2, 3, 5, and 139, it will be seen that 710 indicates a large flexible conduit leading from the exhaust of the motor 212. It conducts the exhaust-air to a nozzle 711, having a curved end with apertures 712, 713, 15 and 714, all disposed in a direction to permit streams of air to blow against the work. The grooved end of the nozzle partially encircles the work, as shown in Fig. 139. This nozzle rests upon a coupling 715, of which mention 20 will be hereinafter made. It may be depressed to permit the passage of a drill on the turret, and to this end it is equipped with a cam-plate 716. (See Figs. 2 and 139.) After- 25 ward it is raised by a spring 1717, the action of which I will explain. I have hereinbefore explained the action of the air and my reason for conducting the same from the exhaust of the air-motor and emitting it through a relatively large aperture, for I find that where 30 the air is emitted from a contracted or reduced aperture it is increased in temperature and by the time it reaches the tool is incapable of dissipating the heat. Therefore I take the exhaust, as said, just as it comes 35 from the motor, after having pushed a resisting piston, and conduct it into close proximity to the tool and work, and by experimentation I have observed I am enabled to dispense in most cases with the use of oil, as 40 the streams of air are at such a relatively low temperature that the heat generated by the frictional engagement of the tool and work is rapidly dissipated.

45 In many cases it may be desirable or perhaps convenient to use oil, especially on steel-work, and therefore I combine with my air-conduit a nozzle or conduit for the oil, so that air and oil may be used alternately or simultaneously. The oil-nozzle is indicated at 717, 50 and it has a bent end 718, which passes through the end of the nozzle 711 and delivers the oil at a very short distance from the point of engagement of the tool with the work. The other end of this nozzle is pivotally connected 55 by a coupling 715 with a joint 719, swiveled to the top of the lathe-carriage, so that the two nozzles have a universal movement. Oil is introduced into the joint through a conduit 720, leading from a convenient source 60 of oil-supply. In order to hold the delivering-apertures of the nozzles in proper position with respect to the tool and the work, I provide the coupling 715 with an arm 721, which is held yieldingly by a spring 1717 65 against the shield 722, which is attached to the carriage and covers one of the shears. This shield is illustrated in my Letters Pat-

ent No. 635,887. The other end of the spring is attached to a stud 723, rising from the carriage.

70 Of course it will be obvious that it is not essential to my invention that I should take the refrigerating-air from the air-motor on the lathe, as I may pipe it from any convenient motor or from any apparatus where it is 75 reduced in temperature. I regard it as a desirable thing to have the apertures through which the oil and the air are delivered to the work as close to the point of engagement of the tool and work as possible, and to this end 80 I employ a cam 716 and the spring 1717, by which the oil and air pipes automatically position themselves as each tool is moved by the turret to operative position. Considered as an oil device alone it has the advantage of 85 discharging the oil directly on the work at the point of the tool instead of at some distance from above, where the stream is subject to deflections by gusts of air, &c.

90 *Motor control.*—In addition to these various features I provide mechanism for controlling the operation of the motor from which power is transmitted to the work-carrier or chuck-carrying spindle. I have not illustrated in detail the link mechanism by which 95 the action of the motor-valve is controlled, as any desired form may be used. I indicate conventionally in Fig. 3 a valve-controlling link 850, to which is connected a rod 851, projecting forwardly through the bed and having on its front end pins 852 852, (see Fig. 101,) operated by stops on the controller. The stops in this instance consist of segmental lugs 853, adjustable in radial slots 854 on the stop-carrier 855. The lugs are all connected by intermediate lugs 856, having a pin-and-slot connection therewith and adjusted radially of the stop-carrier 855 thereby. These segmental lugs form, as it were, a continuous cam for engaging the pins 852 on the 105 rod 851 and adjusting said rod longitudinally to vary the position of the link 850, and thereby directly control the transmission of fluid to the motor to increase or decrease the power transmitted or transformed thereby. These 110 stops are adjusted in accordance with the nature of the operation performed by each tool on the lathe. For instance, it requires much more power to sink a drill into the work than to turn or reduce the thickness of the work, 115 and therefore I provide for driving the spindle with greater power when the drill on the turret reaches operative position. Thus while the controller is driven by the motor it directly governs the action of the motor so far as the 120 driving power transmitted is concerned.

125 *Operation:* It is unnecessary to describe in detail the exact operation of the machine, for that varies in accordance with the work which is accomplished by the tools. It may 130 be stated, however, that the turret is moved backward and forward to present the various tools to the work in proper sequence, the controller being allowed to rotate by the escape-

ments to operate the valve mechanism. After the work is properly turned, shaped, or bored out the cutting-off tool is operated, the receiver being moved into position to catch the work when it is severed. As the severing-tool reaches its lowest position the chuck is opened and the roller-feed advances the stock until it is stopped by the device described, and the chuck is closed, the work-receiver being moved back to inoperative position, thus completing one cycle of operations for the machine.

Having thus explained the nature of my invention and one of the embodiments thereof, without having attempted to set forth all of the forms in which it can be made and all of the modes for its use, what I claim is—

1. A fluid-operated lathe comprising a turret, a valve mechanism, a plurality of stops adapted to control the valve mechanism, a member adapted to engage said stops in predetermined order, and provisions whereby said member is positioned with respect to said stops by the turret.

2. A fluid-operated lathe comprising a turret, a fluid-operated element, a valve mechanism for controlling the supply of fluid, a plurality of stops for operating said valve to partly cut off the supply of fluid to retard the speed of the fluid-operated member, a member adapted to engage any one of said stops at a predetermined point in the travel of the turret-carriage, and provisions whereby said member is positioned by the turret.

3. In a metal-working machine having a plurality of automatic devices for performing successive operations upon the work, a tool-holder, automatic means for moving said holder toward the work, and automatic mechanism for rendering inactive said holder-moving means upon failure of said automatic devices to perform their functions.

4. In an automatic turret-lathe having automatic devices for effecting successive operations on the work, a carriage, a turret on the carriage, carriage-advancing means, mechanism for rendering said carriage-advancing means inactive upon failure of said automatic devices to perform their functions, and provisions whereby said mechanism is controlled by said turret.

5. In a lathe having automatic devices for effecting successive operations upon the work, a tool-holder, means for advancing said tool-holder toward the work, a cutting-off tool, automatic mechanism for rendering said means inactive upon failure of said automatic devices to perform their functions, and provisions whereby said mechanism is controlled by said cutting-off tool.

6. In a lathe having automatic devices for effecting successive operations on the work, a tool-holder, means for advancing said tool-holder toward the work, a controller adapted to render said means active or inactive, and mechanism whereby said controller renders said means active when said devices perform

their allotted functions and renders said means inactive when said devices fail to perform said functions.

7. A turret-lathe having a carriage, a turret thereon adapted for the reception of a plurality of tools, means for advancing the carriage toward the work, a plurality of trip members equal in number to the tools and adapted to render the carriage-advancing means active, a member adapted to coact with said trip members, and provisions whereby said member is positioned with relation to said trip members by said turret.

8. In a lathe having automatic devices for effecting certain operations on the work, a carriage, means for advancing the carriage toward the work, a plurality of trip members each adapted when in predetermined position to render active said advancing means, and provisions whereby said automatic devices automatically control the position of said trip members.

9. In a turret-lathe having automatic devices for effecting certain operations on the work, a carriage, a turret on said carriage having a plurality of tools, means for advancing the carriage toward the work, a plurality of trip members equal in number to said tools, automatic mechanism whereby said trip members when in predetermined position render active the carriage-advancing means, and provisions whereby said automatic devices control the position of said trip members.

10. A turret-lathe having a carriage, a turret thereon, means for advancing the carriage toward the work, a member, provisions whereby said member is positioned by the turret, a plurality of trip-pins adapted to coact singly with said member, and provisions whereby the coaction of a trip-pin and said member renders active said carriage-advancing means.

11. A turret-lathe having a carriage, a turret thereon, means for advancing the carriage toward the work, a member, provisions whereby said member is positioned by the turret, a plurality of trip-pins adapted to coact singly with said member, means whereby said trip-pins are governed in position with relation to said member by said carriage, and provisions whereby the coaction of said member and a trip-pin renders active said carriage-advancing means.

12. A turret-lathe having a carriage, a rotatable turret thereon, means for moving said carriage, a turret-locking device, a plurality of trip-pins, one for each position of the turret, a member adapted to coact with said trip-pins in succession as the turret completes one rotation, provisions whereby said member is positioned by said turret and is actuated by said turret-locking device, and provisions whereby the coaction of said member with one of said trip-pins governs the operation of said carriage-moving means.

13. A turret-lathe having a carriage, a turret thereon, means for moving said carriage, a turret-locking device, a movable member,

provisions whereby said member is positioned by the turret, a plurality of trip-pins arranged in predetermined order across the path of said member and adapted to be engaged in succession by said member, provisions whereby said trip-pins control the action of the carriage-moving means, and provisions whereby the turret-locking device actuates said member to cause it to coact with the trip-pins.

14. A turret-lathe having a carriage, a turret thereon, means for moving said carriage, a movable turret-locking pin, and mechanism whereby said pin, when moved to locking position, renders active said carriage-moving means.

15. A turret-lathe comprising a carriage, a turret thereon, carriage-moving means, a plurality of trip-pins, provisions whereby said trip-pins control the action of said carriage-moving means, a member adapted to operatively coact with said trip-pins, provisions whereby said member is positioned by the turret, a cutting-off tool and provisions whereby the coaction of said trip-pins with said member is controlled by said cutting-off tool.

16. A turret-lathe comprising a carriage, a turret thereon, carriage-moving means, a plurality of trip-pins, provisions whereby said trip-pins govern the action of said carriage-moving means, a member adapted to operatively coact with said trip-pins, provisions whereby said member is positioned by the turret, and provisions whereby the carriage controls the coaction of said trip-pins with said member.

17. A turret-lathe comprising a carriage, a turret thereon, carriage-moving means, a plurality of trip-pins, provisions whereby said trip-pins control the action of said carriage-moving means, a member adapted to operatively coact with said trip-pins, provisions whereby said member is positioned by the turret, work-feeding mechanism, and provisions whereby the coaction of said trip-pins with said member is controlled by said work-feeding mechanism.

18. A turret-lathe comprising a carriage, a turret thereon, carriage-moving means, a plurality of trip-pins, provisions whereby said trip-pins control the action of said carriage-moving means, a member adapted to operatively coact with said trip-pins, provisions whereby said member is positioned by the turret, a cutting-off tool, work-feeding mechanism, and provisions whereby the coaction of said trip-pins with said member is controlled by said cutting-off tool and said work-feeding mechanism.

19. A turret-lathe having a turret, a carriage therefor, means for reciprocating the carriage, a series of trip-pins adapted to control the operation of said means, a hammer adapted to actuate said trip-pins, and provisions whereby said hammer is positioned by said turret.

20. A turret-lathe having a turret, a carriage therefor, carriage-advancing means, a

plurality of trip-pins, provisions whereby said trip-pins render active said carriage-advancing means, a member for actuating said trip-pins, and means actuated by the turret for positioning said member relatively to said trip-pins.

21. A turret-lathe having a turret, a carriage therefor, mechanism for feeding the carriage, means for automatically starting said carriage-feeding mechanism, a turret-locking device, and a member adapted to be operated by the turret-locking pin for governing the said starting means.

22. A turret-lathe having a turret, a carriage, mechanism for feeding the carriage, means for automatically starting said carriage-feeding mechanism, a plurality of stops for holding the starting means against movement, a member for releasing said starting means, and provisions whereby said member is controlled by said turret.

23. A turret-lathe having a turret, a carriage, mechanism for feeding the carriage, means for automatically starting said carriage-feeding mechanism, a turret-lock, a plurality of stops for holding the starting means against movement, a member, provisions whereby said member is controlled by the turret, and mechanism whereby said member is operated by the turret-lock to release said starting means.

24. A turret-lathe having a turret, a carriage, carriage-feeding means, mechanism for automatically starting said carriage-feeding means, a series of stops and a latch member adapted to be engaged with said stops in succession for holding said automatic starting mechanism inactive, a member adapted to disengage said latch member from said stops, and provisions whereby the action of said disengaging member is controlled by the turret.

25. A turret-lathe having a turret having a plurality of tools, a carriage therefor, carriage-feeding means, a series of revolving stops adapted to control said means, there being one stop for each tool on the turret, a latch member adapted to engage the stops singly, and means whereby the rotation of the turret controls the operation of the said member.

26. A turret-lathe having a turret, a carriage therefor, carriage-moving means, a turret-lock, a stop-carrier, a swinging member to engage in succession a series of stops on said carriage, a releasing member actuated by the turret-lock for releasing said member from a stop, and provisions whereby said stop-carrier controls said carriage-moving means.

27. A turret-lathe having a turret, a carriage, carriage-moving means, a turret-lock, a carrier equipped with a series of stops, provisions whereby said carrier controls said carriage-moving means, a member for engaging said stops in succession, a releasing member, means whereby said releasing member is positioned by the turret and means whereby said releasing member is actuated simultaneously.

ously with the turret-lock for releasing the stop-engaging member.

28. A turret-lathe having a carriage, carriage-moving means, a turret, a turret-lock, a carrier provided with a series of stops, provisions whereby said carrier controls said carriage-moving means, a member engaging said stops successively, a releasing member and provisions whereby said releasing member is positioned by the turret and actuated by the turret-lock.

29. In a metal-working machine having a plurality of instrumentalities for operating on the work, a carrier provided with a series of stops, provisions whereby said carrier controls the operation of said instrumentalities, a latch engaging said stops successively, a series of trip-pins to release the latch, and means for actuating said trip-pins to release the latch from the stops.

30. In a metal-working machine having a plurality of instrumentalities for operating on the work, a carrier provided with a series of stops, provisions whereby said carrier controls the operation of said instrumentalities, a latch engaging said stops successively, a series of trip-pins to release the latch, and an automatic hammer for actuating the trip-pins.

31. A turret-lathe having a carriage, carriage-moving means, a turret with tools thereon, a carrier provided with a series of stops, provisions whereby said carrier controls said carriage-moving means, a latch engaging said stops in succession, trip-pins on the carrier, one for each tool on the turret, means independent of the turret for moving said stop-carrier, a member for actuating the said trip-pins in succession, and provisions whereby said member is positioned by said turret.

32. In a turret-lathe having a plurality of instrumentalities for effecting successive operations on the work, a carriage, a turret thereon, tools on the turret, means for reciprocating the carriage, a carrier having a trip-pin for each turret-tool, means for moving said carrier, a movable member adapted to register with said trip-pins successively, means whereby said member is positioned with respect to said trip-pins by the turret, and mechanism whereby the carriage-reciprocating means is rendered active when said member engages a predetermined trip-pin on the carrier.

33. A turret-lathe having a plurality of instrumentalities for effecting successive operations on the work, a carriage, a turret thereon, tools on the turret, a turret-lock, means for reciprocating the carriage, a carrier having a trip-pin for each turret-tool, means for moving said carrier, a movable member adapted to register with said trip-pins successively, means whereby said member is positioned with respect to said trip-pins by the turret, mechanism whereby the carriage-reciprocating means is rendered active when said member engages a predetermined trip-pin on the carrier, and provisions whereby said mem-

ber is caused by said turret-lock to engage a trip-pin when it is properly positioned with respect thereto by the turret.

34. In a metal-working machine having automatic instrumentalities for effecting successive operations on the work, a rotary carrier having a series of stops, provisions whereby said carrier controls the operation of said instrumentalities, a latch adapted to arrest said stops successively, a plurality of trip-pins on said carrier adapted to be successively registered with said latch, and means for actuating said trip-pins to release a stop from the latch.

35. In a turret-lathe having automatic instrumentalities for effecting predetermined operations on the work, a turret, means for rotating said turret, a rotary controller, provisions whereby said controller governs the operation of said instrumentalities, a motor for rotating said controller independently of the rotation of the turret, and means whereby the controller regulates the operation of the motor.

36. In a turret-lathe having automatic instrumentalities for effecting predetermined operations on the work, a rotatable controller, means whereby said controller governs the operation of said instrumentalities, a fluid-operated motor having a valve mechanism, provisions whereby the said motor rotates the controller, and means on the controller for governing the action of the said valve mechanism.

37. In a turret-lathe having automatic instrumentalities for performing predetermined operations on the work, a carriage, a turret, means for rotating the turret, a rotary controller, means whereby said controller governs the operation of the said instrumentalities, the work-carrier, a motor, and mechanism whereby said motor actuates the controller and the work-carrier, and means on the controller for automatically varying the power of the motor.

38. A lathe having a rotatory work-holder, a rotatable turret, a plurality of belt-driven pulleys for the work-holder, a belt-shipper, means for automatically operating said shipper, and provisions whereby said means is controlled by the turret.

39. A lathe having a rotatory work-holder, a rotatable turret, a plurality of belt-driven pulleys for the work-holder, a belt-shipper, means for automatically actuating said shipper, a rotary controller for governing the operation of said actuating means, and provisions whereby said controller is governed by the turret.

40. A lathe having a controller, means for yieldingly rotating said controller, means for automatically stopping the controller, a work-holder, a plurality of belt-driven pulleys for the work-holder, a belt-shipper, and means whereby the controller governs said belt-shipper.

41. A lathe having a rotatory work-holder,

a plurality of belt-driven pulleys for the work-holder, a belt-shipper, a carriage, a turret thereon, a controller for the belt-shipper, and provisions whereby said controller is governed by both the turret and the carriage.

42. A lathe having a rotatory work-holder, a plurality of belt-driven pulleys for the work-holder, a belt-shipper, a cutting-off tool, a controller for the belt-shipper, and provisions whereby said controller is governed by the cutting-off tool.

43. A metal-working machine having a fluid-operated tool, a throttle for retarding the flow of fluid to said tool, and means for automatically maintaining a net difference in pressure on the two sides of the throttle.

44. A metal-working machine having a fluid-operated tool, a liquid-tank, a conduit leading from the tank to the tool, a conduit for conducting air to the tank, a throttling device, and a valve mechanism for opening and closing the conduits for the air and liquid, and also for governing the throttling device.

45. A metal-working machine having a fluid-operated tool, a liquid-tank, and a valve-casing containing mechanism for governing the passage of fluid to the tank and the passage of liquid to said tool, and also containing a throttle for retarding the flow of liquid to the said tool.

46. In a fluid-operated metal-working machine, a fluid-operated carrier, a throttle for retarding the passage of fluid under pressure to move said carrier, and a pressure-regulator for automatically maintaining a net difference in pressure on both sides of the throttle.

47. In a metal-working machine, a tool, a piston, connections between said tool and said piston, a cylinder for said piston, and a valve mechanism to control the supply of fluid to said cylinder comprising a chamber having an inlet-port and an outlet-port, a valve controlling the inlet-port and a spring-pressed diaphragm in said chamber operatively connected to said valve, an adjustable throttle in said outlet-port, and a conduit connecting the spring side of the diaphragm with the cylinder side of the outlet-port whereby an increase of pressure in the cylinder acts to raise the valve in the inlet-port and maintain a constant net difference in pressure on opposite sides of the outlet-port.

48. A turret-lathe comprising a bed, a turret, a substantially vertical cylinder located within the sides of the bed, a plunger in said cylinder, and a cutting-off tool in the upper end of said plunger.

49. A turret-lathe comprising a bed, a turret slideable on the bed, a cutting-off tool normally located between the sides of the bed below the plane of travel of said turret, and means for operating said tool.

50. A turret-lathe comprising a bed, a turret slideable on the bed, a cutting-off tool normally located between the sides of the bed below the plane of travel of said turret, means for operating said tool, and provisions where-

by the tool returns to original position by gravity.

51. A lathe having a cutting-off tool located 70 below the work, a plunger for operating said tool, and guides for said plunger.

52. A lathe having a cutting-off tool, means for actuating said tool, a controller for governing the operation of said means, mechanism for automatically rotating said controller, and a device supplemental thereto for causing a variation in the feeding movement of said tool, and provisions whereby said device is actuated by said actuating means. 80

53. A lathe having a cutting-off tool, fluid-operated means for actuating said tool including a valve, a controller for operating said valve, mechanism for automatically rotating said controller, and an automatic supplemental device for operating said valve to reduce the supply of fluid to said fluid-operated means. 85

54. A lathe having fluid-operated means including a cylinder, a plunger having a cutting-off tool connected thereto, and a valve; a controller for operating said valve; means for rotating said controller; and means actuated by said plunger for governing said controller. 90

55. A turret-lathe having a toothed bar and a rotatory member having cam-teeth for rotating the turret, the crowns of the teeth of said member being at different radial distances from the axis of said member whereby a differential movement is imparted to said turret. 100

56. A metal-working machine having automatic instrumentalities for effecting operations on the work, a controller, provisions whereby the said controller governs the operation of said instrumentalities, and a device governing the actuation of said controller and including two vibratory members having a fluid connection. 105

57. In an automatic metal-working machine having automatic instrumentalities for effecting certain operations on the work, mechanism for actuating the several instrumentalities, and means for controlling the said operations, said means including two movable 115 members and a column of fluid connecting said members whereby the actuation or vibration of one member is transmitted through the column of fluid to the other member.

58. In an automatic metal-working machine having automatic instrumentalities for effecting operations on the work, and mechanism for actuating the several instrumentalities, a device for controlling the operation of said instrumentalities, and a fluid connection between said devices and said instrumentalities whereby the latter govern the action of the former. 125

59. In a metal-working machine having an automatic instrumentality for effecting a certain operation on the work, and mechanism for actuating the several instrumentalities, means for controlling said instrumentality, said means including a fluid-conduit having 130

movable members, the vibration or action of one of which through a consequent variation in pressure of the contained fluid, effects the vibration or action of the other, and provisions whereby said instrumentality actuates one of said members.

60. In a metal-working machine having automatic instrumentalities for effecting certain operations on the work, a rotary controller for controlling the action of said instrumentalities, an escapement for said controller, a fluid-transmitter, and provisions whereby said transmitter may be operated by any one or more of said instrumentalities for effecting the operation of the escapement.

61. In a metal-working machine having automatic instrumentalities for effecting certain operations on the work, a rotary controller for controlling the action of said instrumentalities, an escapement for the controller, and a fluid-containing conduit for transmitting an impulse to the escapement.

62. A lathe comprising a tool-holder, means for reciprocating said tool-holder, a fluid-conduit having a movable member adapted to be engaged by said tool-holder, and a second movable member adapted to be actuated or vibrated by the fluid contained in said conduit, and provisions whereby said second member controls the operation of said reciprocating means.

63. A turret-lathe comprising instrumentalities for effecting a sequence of operations on the work, a controlling member for controlling the operation of said instrumentalities, and a closed fluid-conduit having movable members at the ends for governing the controlling member.

64. An automatic turret-lathe having automatic instrumentalities for effecting certain operations on the work, actuating mechanism therefor, and a system of control for said actuating mechanism including a closed fluid-conduit having a diaphragm at each end whereby the impulses of one diaphragm are transmitted to the other.

65. An automatic turret-lathe comprising a plurality of instrumentalities for automatically effecting certain operations on the work, a rotatory controller, provisions whereby said controller controls the operation of the said instrumentalities, an escapement for the said controller, and a closed fluid-conduit having a movable member at each end, one of said members governing the action of said escapement.

66. An automatic lathe comprising a tool-holder, means for reciprocating the tool-holder, a controller for governing the action of the tool-holder, an escapement for said controller, and means whereby said escapement is controlled by the said tool-holder, said means including a closed fluid-conduit with a member at one end for actuating the escapement, and a member at the other end adapted to be actuated by the tool-holder.

67. An automatic metal-working machine

comprising a cutting-off tool, means for actuating said tool, a controller for governing said actuating means, a fluid-operated escapement for said controller, and means whereby said escapement is governed by said cutting-off tool.

68. An automatic turret-lathe comprising a controller, a fluid-operated escapement therefor, and work-feeding mechanism for governing the escapement.

69. An automatic turret-lathe comprising a controller, a turret-carriage, a work-feeding mechanism, a cutting-off tool, an escapement for the controller, and means whereby said escapement is governed by said carriage, said mechanism and said tool.

70. An automatic turret-lathe comprising a controller, a turret-carriage, a work-feeding mechanism, a cutting-off tool, a fluid-operated escapement for the controller, and means whereby said escapement is governed by the turret-carriage, the work-feeding mechanism and the cutting-off tool in predetermined sequence.

71. An automatic lathe having a turret-carriage, carriage-reciprocating mechanism, a controller for said mechanism, a fluid-operated escapement for said controller having a valve, and means governed by the turret-carriage for operating said valve, said means including a closed fluid-conduit having movable members at its end.

72. A turret-lathe having a controller, a fluid-operated escapement for said controller having a valve, a diaphragm for operating said valve, a carriage, carriage-reciprocating mechanism governed by said controller, and a driver whereby said carriage actuates said diaphragm.

73. An automatic lathe having a controller, a fluid-operated escapement having a valve, and a closed fluid-conduit having a member actuated by the variation of pressure of the fluid within said conduit for operating said valve.

74. An automatic lathe having a controller, a fluid-operated escapement having a valve, and a closed fluid-conduit having a diaphragm at each end, one of said diaphragms actuating said valve, and the other being in position to receive a vibration or impulse from an operative part of the lathe.

75. A lathe having a movable instrumentality, a controller for governing said instrumentality, and an escapement for the controller including a stop-carrier, a plurality of stops, and a movable member having provisions for releasing a stop and being thereby moved to position by said stop, to engage the next succeeding stop.

76. A lathe having a movable instrumentality, a controller for governing said instrumentality, a stop-carrier thereon having a series of stops, and a rotary latch having means to engage and release said stops in succession.

77. A lathe having a movable instrumentality, a controller for governing said instru-

- mentality, a stop-carrier thereon, having a series of stops, and a toothed member adapted to engage and release said stops in succession. 70
78. A lathe having a movable instrumentality, a controller for governing said instrumentality, a stop-carrier having a series of stops, and a rotary spirally-grooved latch for engaging and releasing said stops in succession. 75
79. An automatic metal-working machine comprising a carriage, mechanism for reciprocating said carriage, a rotatable controller having provisions for rendering active said reciprocating mechanism, a member in operative relation to said controller to govern the action thereof, a member adapted to be operated by said carriage, and a fluid connection between said members. 80
80. A metal-working machine having automatic instrumentalities for operating on the work, a yieldingly-driven controller having provisions for rendering said instrumentalities active or inactive, a member for holding said controller against movement, a member adapted to be operated by one of said instrumentalities, and a fluid connection between said members. 85
81. A turret-lathe comprising a bed, a carriage, a piston and cylinder located below the upper face of the carriage for moving the latter, a fluid-chamber located on the head of the bed above the plane of the cylinder, and a meter for controlling the supply of fluid from the said chamber to said cylinder. 90
82. A turret-lathe comprising a bed, a carriage, a piston and cylinder located below the upper face of the carriage for moving the latter, separate fluid-chambers mounted on the head of the bed and connected respectively to the opposite ends of the cylinder, a source of fluid-supply leading to said chambers, a meter between said chambers and said cylinder, and valve mechanism for controlling the passage of the fluid. 95
83. A turret-lathe comprising a bed, a carriage, a piston and cylinder located below the upper face of the carriage for moving the latter, separate fluid-chambers mounted on the head of the bed and connected respectively to the opposite ends of the cylinder, a source of fluid-supply leading to said chambers, a meter or regulator, and a valve having provisions for deflecting liquid from said chambers directly to said cylinder or through said meter. 100
84. A turret-lathe comprising fluid-operated mechanism, a tool-slide, a piston and cylinder, a fluid-tank, a meter, a valve mechanism, and a casing containing said meter and said valve mechanism, said casing being secured to said tank. 105
85. A turret-lathe comprising fluid-operated mechanism, a fluid meter or regulator, separate fluid-chambers having ports leading therefrom, conduits leading to the opposite ends of the cylinder of said fluid-operated mechanism, ducts leading to the meter, and a valve for connecting said ports with said conduits, or with said ducts, to cause the fluid to flow to the cylinder directly or through the meter. 110
86. A fluid-operated lathe comprising a tool-holder, a cylinder and piston for moving said tool-holder, a source of fluid-supply, a meter, and a cushioning device for causing the fluid to exert a practically continuous pressure on the piston. 115
87. A fluid-operated lathe comprising a tool-holder, a cylinder and piston for moving said tool-holder, a fluid meter or regulator having a reciprocating measuring member for delivering charges of fluid to said cylinder, and means for cushioning the charges of fluid delivered by the meter, for effecting an even pressure against the piston. 120
88. A fluid-operated lathe comprising a tool-holder, a piston and cylinder for moving said tool-holder, a fluid meter or regulator having a reciprocating measuring member for delivering charges of fluid to said cylinder, and means interposed between the meter and the cylinder for effecting a continuous uniform flow of liquid to said cylinder. 125
89. A fluid-operated lathe comprising a tool-holder, a piston and cylinder for moving said tool-holder, means for delivering intermittent charges of fluid to said cylinder, and a cushioning device having a yielding member for effecting a continuous flow of fluid into said cylinder. 130
90. A fluid-operated lathe comprising a tool-holder, a piston and cylinder for moving said tool-holder, means for delivering intermittent charges of fluid to said cylinder, and a cushioning device having a yielding member for effecting a continuous flow of liquid into said cylinder and also having means for varying the tension on said yielding member. 135
91. A fluid-operated lathe comprising a tool-holder, a piston and cylinder for moving said tool-holder, means for delivering intermittent charges of fluid to said cylinder, and a cushioning device having a yielding member for effecting a continuous flow of fluid into said cylinder and also having means for limiting the extent to which said member can yield. 140
92. A turret-lathe having a tool-holder, a carriage, a piston and cylinder for reciprocating said carriage, means for delivering fluid in intermittent charges, and yielding means for effecting a continuous flow of fluid to said cylinder in the interval between the delivery of two charges, but weak enough to yield under the hammer effect of each charge. 145
93. A fluid-operated lathe comprising a controller having stops, a valve, and means whereby said valve is moved first in one direction and then in the other by said stops. 150
94. A fluid-operated lathe comprising a controller having stops, a valve having means whereby it is moved in one direction directly by a stop, and having intermediate means whereby it is moved in the opposite direction by a stop. 155

95. A fluid-operated lathe comprising a rotary controller having stops, a valve having its axis of movement parallel with the axis of the controller, and means whereby said valve is moved in opposite directions alternately by said stops. 5
96. A metal-working machine having conduits for delivering both oil and refrigerated air on the work, said conduits being arranged 10 to have a common nozzle.
97. A turret-lathe having a rotary turret having tools thereon and means for delivering the heat-dissipating fluid on the work including a yielding nozzle which yields to permit 15 the passage of a tool on the turret.
98. A turret-lathe having means for delivering a heat-dissipating fluid on the work, including a spring-held nozzle having a cam arranged to be engaged by a tool on the turret 20 for the purpose of displacing said nozzle to permit the passage of said tool.
99. A turret-lathe having a series of stops for governing the travel of the tool-carriage, an automatic guard for preventing the access 25 of chips or cuttings to said stops, and provisions for intermittently connecting said guard to the tool-carriage.
100. A turret-lathe having a bed, a tool-carriage, means for moving said carriage, a series of stops for governing the travel of the 30 tool-carriage, said stops being supported by the bed, a guard and provisions for intermittently connecting said guard to and disconnecting it from the carriage, whereby said 35 guard is moved automatically to prevent the access of foreign matter to said stops.
101. A turret-lathe having a tool-carriage, means for reciprocating said carriage, a series of stops for governing the travel of the 40 tool-carriage, a guard movable with the carriage for covering said stops, and provisions for intermittently connecting said guard to the tool-carriage and to the lathe-bed alternately.
102. A turret-lathe having a tool-carriage, a receiver for the finished work, and means actuated by the carriage for moving said receiver positively toward and from operative 45 position under the work.
103. A turret-lathe having a turret, a carriage, carriage-moving mechanism, a controller for the carriage rotated independently of the turret, and a receiver for the finished work actuated by the turret, said receiver being governed in its operation by said controller. 50
104. A turret-lathe having a turret, a carriage, carriage-moving mechanism, a controller for the carriage rotated independently 55 of the turret, a receiver for the finished work actuated by the turret, and a stop on the controller for governing the operation of said receiver.
105. A turret-lathe having a turret, a turner 60 on said turret, and a templet movable into operative position to control said turner.
106. A turret-lathe having a turret, a turner 65 on said turret, and provisions for moving said templet automatically into operative position to control said turner. 70
107. A turret-lathe having a turret, a turner on said turret, and a templet normally located in a plane above said turner, but movable into operative controlling relation thereto.
108. A turret-lathe having a turret, a turner 75 on said turret, a templet for controlling said turner, and fluid-operated mechanism for moving said templet to operative position.
109. A turret-lathe having a turret, a turner 80 on said turret, a templet for controlling said turner, mechanism for moving said templet to operative position, and a controller for governing the action of said mechanism.
110. A turret-lathe having a turret, a turner 85 on said turret, a templet for said turner, and means for moving said templet into and out of operative position.
111. A turret-lathe having a turret, a turner 90 on said turret, a templet for said turner, and interconvertible manually or automatically controlled means for moving said templet into operative position when said turner is moved by the turret to cutting position.
112. In a lathe, the combination with a 95 sliding carriage and a turret rotatable thereon, of a turning-tool having a standard attached to said turret to rotate therewith, a cutter, an arm supporting the cutter at its free end and extending in the direction of the work, and a pivot for said arm on said standard transverse to the axis of the work, whereby said tool may be moved to operative position with relation to the work and the cutter swung toward and from the work, and a templet adapted to be moved to operative relation to said arm. 100
113. In a lathe, the combination with a 105 sliding carriage, a turret rotatable thereon, and a templet independent of said turret, of a turning-tool having a base adapted to be attached to said turret, a cutter, a carrier oscillatory about an axis transverse to the axis of the work, and having provisions for holding said cutter on its free end, and a member connected to said carrier and adapted to slidingly engage said templet when the turret has been rotated to proper position. 110
114. In a lathe, the combination with a 115 sliding carriage, and a turret rotatable on said carriage, of a turning-tool consisting of a base adapted for attachment to said turret, and a cutter and a back-rest pivoted on said base and movable toward and from each other on parallel axes transverse to the axis of the work, a templet, and provisions whereby said templet controls said cutter and back-rest. 120
115. In a lathe, the combination with a 125 sliding carriage, and a turret rotatable on said carriage, of a turning-tool consisting of a base adapted for attachment to said turret, a cutter, a back-rest, oppositely-swinging carriers for said cutter and said back-rest movable about axes transverse to the axis of the work and means including a templet for si- 130

multaneously moving said carriers in opposite directions.

116. In a lathe, the combination with a sliding carriage, and a turret rotatable on said carriage, of a turning-tool consisting of a base adapted for attachment to said turret, a cutter, two independent work-rests, and means for simultaneously moving said cutter and said work-rests toward or from the work when the turret is in proper position, and a templet adapted to be moved into operative relation to said tool.

117. In a turret-lathe, the combination with a tool-carriage, and a turning-tool thereon having a movable cutter, of a templet, and means for automatically moving said templet into operative relation to the said turning-tool, whereby the said cutter may be governed by the said templet.

118. A lathe comprising a tool-carrier, fluid-

operated mechanism for moving said carrier, and a valve mechanism therefor including a throttle - valve and a pressure - controlling mechanism adapted to maintain a net difference in pressure between the receiving and delivery sides of the throttle, said pressure-regulating mechanism and said valve mechanism being all inclosed in one casing.

119. In an automatic lathe, a spindle-driving motor, a lathe-controlling shaft, and an adjustable cam on said shaft for controlling the speed and direction of rotation of said motor.

In testimony whereof I have affixed my signature in presence of two witnesses.

JAMES HARTNESS.
